UNITED STATES PATENT OFFICE.

ARTHUR J. RAY, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed April 17, 1922. Serial No. 553,677.

The present invention relates in general to automatic telephone systems of the multi-office type, but is more particularly concerned with systems of this character in which the main offices of the system have several smaller exchanges subsidiary to them, the latter being commonly known as sub or satellite exchanges; and the object of the invention may be said to be the provision of sub-office switching equipment embodying new features and novel circuit arrangements which are better adapted than those heretofore used to meet the service requirements of the present time.

More specifically, one of the principal objects is to produce a novel device referred to hereinafter as a switching discriminator. This device introduces a considerable saving in the inter-office trunks, and also decreases the number of switches required in certain classes of connections.

There are other objects of the invention not now specifically mentioned which together with those enumerated above will be described thoroughly hereinafter, reference being had to the accompanying drawings forming part of this specification.

Referring now to the drawings, Figs. 1 and 2 show maps of certain of the exchanges in the system about to be described. Fig. 3 shows the manner in which certain figures of the drawings are to be placed in order that the description of the operation of the system may be followed. Fig. 4 shows a general trunking layout of the system according to the map shown in Fig. 1. Figs. 5-12, inclusive, when placed in the relative positions indicated in Fig. 3, show by means of the conventional circuit diagrams the detailed circuits of the various apparatus and the manner in which the novel results set forth above are accomplished.

The invention is, of course, applicable to various sizes of multi-office telephone systems; however, in the present case it has been illustrated in connection with a six digit system, or one the ultimate capacity of which does not exceed a million lines.

The system disclosed in the present case has ninety main exchanges each having an ultimate capacity of ten thousand lines, and sub-exchanges or satellites varying in size from fifty or one hundred lines to one thousand. In a six digit system of this character

the first two digits dialled select the particular main exchange desired. The third digit determines to which group of one thousand lines a call is going, while the fourth digit selects the particular group of 100 lines which contains the desired called line. Since the sub-exchanges may vary in size from one hundred to one thousand lines, the third or fourth digit, as the case may be, determines the particular satellite exchange called.

In a system of the character outlined above, it often occurs that two or three of these satellite exchanges will be located close together, at some distance from the main exchange to which they are subsidiary and that a second main exchange is situated quite close to the sub-exchanges. Under these conditions there will, in all probability, be trunk lines connecting one or more of the sub-exchanges with the second main exchange as well as with the first. These additional groups of trunk lines may be provided because there is a great deal of traffic from one or more of the sub-offices in the direction of the second main exchange, which makes it more economical to install additional groups of trunk lines from these sub-offices to the second main exchange rather than route the calls which go to points in the general direction of the second exchanges thru the main exchange with which the sub-offices are associated. Under these conditions, all outgoing calls which finally terminate at an exchange located in the general direction of the aforesaid second main exchange will be routed thru that exchange, while all calls in the other direction will be routed through the first main exchange. All incoming calls will be handled thru the first exchange.

In describing the drawings, the general layout of the system will first be explained with reference to the maps of the exchanges, Figs. 1 and 2. In Fig. 1 there is shown a main office designated by the reference character 91 which represents the number of this office in the numbering scheme of the system. The main office 91 has the subsidiary satellite offices 912, 913, and 9181 associated with it. The first two mentioned sub-offices each have an ultimate capacity of one thousand lines, while the last mentioned sub-office is of one hundred lines capacity. At 92 is shown another main office located in fairly close proximity to the sub-exchanges but

at some distance from the main office 91. The lines connecting the various exchanges illustrate the trunk lines in the system and the arrow heads indicate whether connections 5 may be handled in both directions or only in one direction over these trunk lines, thus, the three sub-exchanges 912, 913 and 9181, are connected to the main exchange 91 by trunk lines which are used for calls 10 in the direction of the main exchange and in the direction of the sub-offices and in addition the 913 sub-office is connected with the exchanges 912 and 9181 by trunk lines which are used for calls in either direction. 15 All the above trunk lines may be of the so called two way type or may be two groups of one way trunk lines depending upon what is considered the most advisable in each case. The sub-office 913 is also connected, by means 20 of a group of one way trunk lines, to the main exchange 92 so that calls in the general direction of the main office 92 may be extended without taking a trunk line to the main exchange 91 and thereafter a trunk 25 line from exchange 91 to exchange 92.

In Fig. 2 is shown another situation in which two sub-offices are associated with the main exchange 91 and the trunk lines are so arranged that, in order to call exchange 30 912 from exchange 913, it is unnecessary to go thru the main exchange 91.

Referring now to the trunking diagram shown in Fig. 4, the various trains of switches involved in typical connections in 35 the trunking situation shown in the map, Fig. 1, are illustrated. To give a general understanding of the operation of the invention, the manner in which calls are extended from the sub-office 913 to the various 40 other exchanges will be given with reference to Fig. 4.

For the purpose of the description it will first be assumed that the subscriber at substation A in sub-office 913 desires to call a 45 subscriber at substation A² in the main exchange 91. In order to accomplish this result he will remove his receiver and operate his calling device for the six digits 91826X, the letter X as used in this combination of 50 digits, and as it will be used subsequently, simply indicating that any digit from 1 to 0 may be dialled as the final digit so far as the trunking diagram is concerned, the individual bank contacts of the connector 55 levels not being shown. When the receiver is removed at substation A the primary line switch C is caused to select an idle trunk line leading to a secondary line switch such as C'. The secondary line switch C' is 60 thereupon operated to select an idle trunk line extending by way of a repeater such as R to an incoming first selector E in the main exchange. An idle finder switch such as F is started in operation as soon as the 65 primary trunk line is seized in order to

associate a switching discriminator SD with the seized trunk line. In response to the first digit dialled by the calling subscriber the first selector E in the main exchange raises its wipers opposite the ninth 70 level of bank contacts. The selector E then operates to automatically select an idle trunk line leading to a second selector such as E'. The element N of the switching discriminator SD is operated in synchronism 75 with the selector E in the main exchange and operates to raise its wipers to the level of bank contacts corresponding to the digit dialled. When the calling device at substation A is operated in accordance with the second digit 1 of the called number the second selector E' is caused to raise its wipers 80 opposite the first level of bank contacts. Thereafter the second selector E' is operated to select a trunk line leading to an idle 85 third selector switch which we will assume is the selector E². In the switching discriminator SD the element N responds to the digit 1 and rotates its wipers in on the level of bank contacts to which it was raised by 90

the first digit, that is, the first contact in the ninth level. In response to the third digit 8 the third selector E² raises its wipers to the eighth level of bank contacts and then automatically operates them to select 95 a trunk line leading to an idle fourth selector such as E³. The element M of the switching discriminator SD, in response to the third digit 8, raises its wipers to the eighth level of bank contacts. When the next digit 2 is dialled the wipers of the fourth selector E³ are operated to the second level of bank contacts and are then rotated to select a trunk line leading to 100 an idle connector switch which it will be assumed is the connector H. In the switching discriminator SD the element M responds to the fourth digit of the desired number and rotates its wipers into engagement with the second bank contact on the 110 eighth level. Inasmuch as the digits 9182 determine that the connection is going to the main exchange and not over any one of the by-paths accessible thru the line switches C⁴, C⁵, C⁶, C⁷, and C⁸, the switching discriminator SD has no function to perform and is released. In accordance with 115 the next two digits 6X dialled by the subscriber at substation A the wipers of the connector H are raised vertically to the sixth 120 level and then rotated into engagement with the bank contacts in which is terminated the line of the desired subscriber at substation A².

It will now be assumed the subscriber at 125 substation A desires to call a subscriber at substation A⁴ in the hundred line sub-exchange 9181 whose number is 91817X. In response to the first three digits 918, the first, second and third selectors such as E, 130

E' and E^2 in the main exchange are operated in a manner similar to that described in the preceding connection. The elements N and M of the switching discriminator SD are operated in the same manner as before in response to the digits 918. The fourth selector E^3 is raised to the first level in response to the fourth digit 1 and automatically operates to select an idle trunk line leading to an incoming connector in the sub-exchange 9181 thru a repeater such as R^2 . The element M of the switching discriminator SD also responds to the fourth digit 1 and rotates its wipers into engagement with the first set of bank contacts on the eighth level. It will be noted from the trunking diagram shown in Fig. 1 that the sub-exchange 9181 is located a point midway between exchanges 913 and 91 and also that the exchange 913 has trunk lines extending to exchange 9181. Therefore, in order to reduce the length of trunk lines used, the switching discriminator SD causes line switch C^7 to be automatically operated to select an idle trunk line leading to an incoming connector in the sub-exchange 9181 thru a repeater such as R^7 . The trunk line seized by the line switch C' extending to the main exchange and the selectors E , E' , E^2 and E^3 therein are released as a result of this operation, as is the switching discriminator SD. In response to the last two digits 7X, an incoming connector such as H^3 is operated to complete the connection to the line of the desired substation A^4 .

It will now be assumed that the calling subscriber at substation A desires to communicate with the subscriber at substation A^6 in the thousand line sub-exchange 912 whose number is 91278X. When the receiver is removed, the primary line switch C operates to extend the calling subscriber's line to an idle secondary line switch such as C' . The line switch C' then operates to select a trunk line extending to an idle incoming first selector such as E in the main exchange. When the primary trunk line is seized an idle finder such as F is operated to associate the discriminator SD with said trunk. In accordance with the first two digits 91 a first and a second selector such as E and E' are operated in a manner similar to that above described and the connection is extended to a third selector such as E^2 . The element N of the switching discriminator SD is operated in response to the digits 91 raising its wipers to the ninth level of bank contacts and then rotating them into engagement with the first contact in that level. When the third digit is dialled the third selector E^2 in the main exchange is operated to raise its wipers to the second level of bank contacts and then to rotate them in search of an idle trunk line leading to an

incoming fourth selector in the sub-exchange 912. The element M of the switching discriminator SD is operated to the second level in response to the digit 2 in the manner before described. The number 912 determines that a subscriber in the sub-exchange 912 is being called and, as there are trunk lines extending from the sub-exchange 913, in which the call is originated, to the sub-exchange 912, the switching discriminator SD causes the line switch C^8 to extend the call over an idle trunk line to an incoming fourth selector such as E^6 in the sub-exchange 912. The trunk line extending to the main exchange, the switches operated therein, and the switching discriminator SD, are immediately released. In accordance with the three remaining digits 78X the fourth selector E^6 and a connector such as H^4 are operated to extend the connection to the line of the substation A^6 .

It will now be assumed that the subscriber at substation A in the sub-exchange 913 desires to call the subscriber at substation A^5 in the other main exchange 92. In order to do this the calling subscriber will remove his receiver and operate his calling device for the digits 92556X. When the receiver is removed the primary line switch C and a secondary line switch such as C' operate to select a trunk line extending to an idle incoming first selector switch in the main exchange and an idle finder such as F operates to connect a switching discriminator SD with the selected primary trunk line. In response to the first digit 9 the wipers of the first selector E are raised opposite the ninth level of bank contacts and are then automatically rotated into connection with an idle trunk line leading to a second selector switch such as E' . The element N of the switching discriminator SD in the sub-exchange 913 is caused to raise its wipers opposite the ninth level of bank contacts. When the second digit 2 is called, the second selector E' is operated to the second level and is then caused to select a trunk line extending to an idle incoming third selector such as E^9 in the main exchange 92 by way of the repeater R^2 . The element N of the switching discriminator is also operated in accordance with the digit 2 and, as there are trunk lines extending from sub-exchange 913 to the main exchange 92, the line switch C^6 is operated to select one of these trunk lines and the connection to the main exchange is released as is the switching discriminator SD. When the next four digits 556X are called, an incoming third selector such as E^8 , a fourth selector such as E^{10} , and a connector such as H^5 , are operated in the main exchange 92 to extend a connection to the line of the substation A^5 .

The manner in which connections are ex-

tended to subscribers in the various exchanges adjoining the exchange 913 having been described, the way in which a local connection is established will now be explained. For this purpose it will be assumed that the calling subscriber at substation A desires to call a subscriber at substation A' whose number is 91346X. When the receiver is removed, the line switch C and a secondary line switch C' are operated in the usual manner to select a trunk line extending to an idle first selector which it will be assumed is the selector E in the main exchange. By the operation of an idle finder such as F the switching discriminator SD is associated with the seized primary trunk line. In response to the first two digits 91 of the called number the first selector E and a second selector E' in the main exchange are operated to extend the connection to an idle third selector such as E². The element N of the switching discriminator SD operates to register the first two digits in the same manner as before described. When the third digit 3 is dialled the third selector E² in the main exchange responds and operates to raise its wipers to the third level of bank contacts and then seizes an idle incoming fourth selector E⁴ in the subexchange 913. As the first three digits 913 determine that the connection is going to a local line, the operation of the element M of the switching discriminator SD for the digit 3 causes the line switch C⁴ to be operated to seize an idle trunk line extending to a local fourth selector such as E⁵. The trunk line extending to the main exchange, the operated switches therein and the discriminator SD are released as before.

In response to the three remaining digits 46X, the selector E⁵, and a connector H' are operated in the usual manner to complete the desired connection to the substation A'.

It will be assumed that the subscriber at substation A desires to call the subscriber at substation A' on his own line. In order to accomplish this result the subscriber at substation A will remove his receiver and operate his calling device for the digit 0. In response to the removal of the receiver the line switch C and a secondary line switch such as C' operate as before described. By the operation of an idle finder F, when the primary trunk is seized, a switching discriminator SD is associated with the said trunk. When the digit 0 is called on the calling device, the selector E is operated to raise its wipers to the tenth level. As the tenth level is dead the trunk selecting operation of the first selector is without function. As the element N of the switching discriminator is operated in accordance with the digit 0 which determines

that a subscriber on the same line as that of the substation A is being called, the line switch C⁵ is operated to select an idle ring back device K and the connection to the main exchange and the switching discriminator SD are released. The subscriber at substation A will now replace his receiver upon the switch-hook. By this operation the ring back apparatus K starts functioning and the signals at substations A and A' are rung alternately. When the called subscriber at substation A' answers, the subscriber at substation A is informed of this fact as he is no longer signalled and he will remove his receiver and converse with the subscriber at substation A'.

From the above it will be seen that the greatest economy in the length of trunk lines used in various connections is effected, as the shortest route to the exchange in which the called subscriber's line is terminated is employed in extending connection to that subscriber.

Referring now more particularly to the detailed circuit drawings Figs. 5-12, inclusive, in Fig. 5 there is shown a party line in the upper left hand corner of the drawing having the substations A and A' thereon. The substation A is of the automatic type having the usual talking instrumentalities and a calling device S. The substation A' is similar to the substation A in every respect except that its bell is connected from the opposite side of the line to the ground. The party line comprising conductors 11 and 12 terminates at the exchange in the individual line or trunk selecting switch C.

The line switch C is of the usual rotary type whose wipers have no normal position, always standing in engagement, when idle, with the bank contacts associated with the trunk line last used. The line switch C, in common with a plurality of other line switches of the group, has access to trunk lines leading to secondary line switches, such as the line switch C'. The line switch C' is of the usual rotary type, similar to the line switch C, and has access to trunk lines extending to the main exchange by way of repeaters such as the one shown at R, Fig. 6. 115

Associated with each of the trunk lines to which the line switch C has access, is a relay group similar to the one shown in the drawings at RG. This relay group is adapted to control the starting of an idle finder switch such as F, Fig. 9.

The finder switches, such as F, are of the usual rotary type, and function to associate a switching discriminator, such as the one shown at SD, with the seized primary trunk line.

The starting of an idle finder switch is controlled by a distributor switch, such as the one shown at D, Fig. 9, which is also of the same general mechanical construction as 130

the switches C' and F. The primary trunk line, in addition to terminating in line switch C', has associated with it the rotary line switches C⁴, C⁵, C⁶, C⁷, and C⁸, Fig. 10. The 5 rotary line switch C⁴ has access to local fourth selectors, such as the selector E⁵ shown in Fig. 12. The trunk lines accessible to the line switch C⁵ extend to the ring back apparatus, such as K, Fig. 11. The 10 line switch C⁶ has access to trunk lines which extend to the second main exchange via the repeater R⁶, Fig. 11. The trunk lines accessible to the line switch C⁷ extend by way of repeaters, such as R⁷, to a small 15 sub-exchange of one hundred lines where they terminate in incoming connector switches. The line switch C⁸ has access to trunk lines extending to another nearby sub-exchange of one thousand line capacity 20 where they terminate in incoming fourth selectors by way of repeaters, such as R⁸.

The switching discriminator SD, Fig. 9, is made up of two switches M and N of the usual Strowger vertical and rotary type. 25 These switches differ slightly from the regular Strowger switches in that they are provided with a vertical bank and associated wipers. The vertical bank is so arranged that each vertical bank contact is opposite a 30 level of the usual bank contacts. The switching discriminator SD is operated in response to the impulses sent over the trunk line to the main exchange and determines whether any of the line switches such as C⁴—C⁸, 35 inclusive, will be operated and the connection to the main exchange released.

The repeater R, Fig. 6, has the function of repeating impulses over the trunk line comprising conductors 139 and 140 to the 40 main exchange switches, and also to send impulses back to control the switching discriminator such as SD.

A number of repeaters such as repeater R', Fig. 6, are accessible to the secondary line switch C' and similar switches and are 45 adapted to be connected with only when all the trunks, such as the one comprising conductors 139 and 140, extending to the main exchange are busy. The repeater R' operates to control the switching discriminator 50 in the same manner as the repeaters such as R so that if all the trunks to the main exchange are busy the calling subscriber will 55 not be precluded from extending a call over one of the other paths as provided by the line switches C⁴—C⁸, inclusive.

The selector E, Fig. 6, is of the usual 60 Strowger two wire type and has access to trunk lines extending to second selector switches such as the one indicated at E', Fig. 7.

While the second selector E' is merely indicated in the drawings it will be understood that it is similar to the selector E in 65 all respects except that the circuits are so

arranged that immediately upon a connection being extended to this switch ground is placed upon the release trunk conductor 178 in order to maintain the preceding selector switch in its operated position. The selector 70 E' has access to trunk lines extending to third selector switches such as E² in the main exchange and to trunk lines extending by way of repeaters such as the one shown at R³ to incoming third selector switches in 75 the second main exchange.

The selector switch E² is similar to the selector switch E' and has access to trunk lines extending to fourth selector switches such as E³ in the main office and to trunk 80 lines extending by way of repeaters such as those shown at R⁴ and R⁵ to the one thousand line sub-exchange tributary to the main exchange. The trunk lines extending through the repeater R⁵ are shown terminating in a 85 fourth selector E⁴, Fig. 12, in the sub-office in which the call is originated. The trunk lines extending through repeaters such as the one illustrated at R⁴ terminate in an incoming fourth selector, in the other one 90

The fourth selectors in the main exchange such as the one indicated at E³, Fig. 7, have access to trunk lines leading to local connector switches such as the connector H and to trunk lines extending by way of repeaters such as R² to incoming connector switches in 95 the one hundred line sub-office tributary to the main exchange.

The repeaters R², R³, R⁴ and R⁵ are similar to the repeater R previously described. 100

The connector H is a switch of the usual Strowger type and has access to local subscribers' lines in the main exchange, one of 105 these being shown in the drawings terminating in the bank contacts 343—345, inclusive, and having associated with it the substation A².

The substation A² is similar to the substation A already described. 110

The ring back equipment K, Fig. 11, enables a subscriber on a party line in the sub-office to call another subscriber on his own line.

The repeaters R⁶, R⁷, and R⁸ are similar 115 to repeaters which have already been described.

The local fourth selector E⁵, Fig. 12, has access to connector switches such as H' in the sub-exchange in which the substation A³ 120 is located.

The incoming fourth selector E⁴ Fig. 12, is similar to the selector E, Fig. 6, already 125 described and has its banks multiplied with those of the local fourth selectors such as E⁵.

The connector H', Fig. 12, is identical in all respects to the connector H, Fig. 8, and has access to the lines of the local substations in the sub-exchange, one of these being that of the substation A³. 130

The substation A³ is similar to the substation A, described before, and its line terminates at the exchange in the rotary line switch G³.

- 5 Throughout the drawings, the relays which have slow acting characteristics are denoted by the shading on the lower ends of their cores or else by the solid black portion on the upper ends of their cores. The 10 relays which have cores shaded on the lower end are the usual so-called "slow acting" relays and are slow to fall back but not noticeably slow to pull up. On the other hand, the relays which have the upper ends of 15 their cores shown solid black are slightly slow to pull up, in addition to being slow to fall back.

Having described the drawings and the general manner in which connections are established from the subscriber at substation 20 A to subscribers in the various other exchanges, the detailed circuit operation when these connections are extended will now be described with reference to Figs 5—12, inclusive, these drawings being laid out in the manner shown in Fig. 3. In order to describe these operations, it will first be assumed, as in the general description, that the subscriber at substation A in the sub- 25 exchange 913 desires to call a subscriber at the substation A² in the main exchange, whose number is 91826X. In order to do this the calling subscriber will remove his receiver and operate his calling device S in accordance with the above digits.

When the receiver is removed at substation A a circuit is completed over the line conductors 11 and 12 for the line relay 14 of the individual line switch C. Relay 14, 40 upon energizing, at its armature 25 closes a circuit for the switching relay 13 in series with the motor magnet 15 and at its armature 24 connects the test wiper 27 to the above circuit at the point midway between 45 the switching relay and the said motor magnet. The operation of the rotary line switch C now depends upon whether its wipers 26—28, inclusive, are associated with a busy trunk line or not. Assuming first that the 50 associated trunk line is busy ground will be connected to the test contact engaged by the test wiper 27, the switching relay 13 will be short circuited, and the motor magnet 15, being supplied with direct ground via 55 the said test wiper, will operate as a buzzer to advance the switch wipers step by step in search of an idle trunk line. However, it will be assumed in the present case that when the receiver is removed at substation 60 A the wipers of the line switch C are associated with an idle trunk line and it will be assumed further that this trunk line is the one shown in the drawings terminating the bank contacts 29—31, inclusive. Under 65 these conditions the switching relay 13 is

energized immediately after the energization of the line relay 14. Relay 13, upon operating, at its armature 19 connects ground to the test contact 30 of the seized trunk line in order to prevent the said trunk line from being used for another call, and at armatures 18 and 20 disconnects the line conductors 11 and 12 from the winding of the line relay 14 and from ground, respectively, and extends them by way of wipers 26 and 28, bank contacts 29 and 31, armatures 47 and 49, and their back contacts, armatures 70 and 74 and their back contacts, and thru the winding of the line relay 66 to battery and to ground, respectively, in the secondary line switch C'.

Immediately upon the extension of the calling subscriber's line to secondary line switch C', as above described, the line relay 66 thereof is energized. Relay 66 at its armature 77 closes a circuit for the switching relay 65 and the motor magnet 67 in series, at armature 76 connects the test wiper 81 to the above circuit at a midpoint between the switching relay and the motor magnet and at armature 75 places ground upon the release trunk conductor 78, thereby establishing a holding circuit for the primary line switch C. This holding circuit may be traced from ground on release trunk conductor 78 by way of normally closed springs controlled by armature 48, test contact 30, test wiper 27, armature 19 and its front contact, thru the winding of the switching relay 13 and thence thru the winding of the motor magnet 15 to battery. This holding circuit serves to maintain the switching relay 13 energized throughout the connection and it will be understood that it is established before the slow acting line relay 14 has had time to deenergize. A branch of this holding circuit also extends by way of the private normal conductor 22 to multiply connected test contacts in the banks of connector switches which have access to the line of the substation A whereby the said line is protected from intrusion during existence of the connection.

The energization of the line relay 66 of the secondary line switch C' causes the trunk selecting operation of this switch to take place in substantially the same manner as that of the primary line switch C.

It will be recalled that when the switching relay 13 of the primary line switch C energized ground was placed upon the test contact 30. This ground causes the energization of the relay 40 in the relay group RG associated with the seized trunk line. Relay 40, upon energizing, removes ground from the conductor 57 thereby rendering the trunk line in use having the multiple test contacts such as 461 accessible to the finder switches such as F. Another result of the energization of the relay 40 is that a

circuit is completed extending from ground by way of armature 46 and its back contact, front contact and armature 44, conductor 55, wiper 442 of the distributor switch D, bank contact 480 and thence thru the winding of the starting relay 409 of the finder switch F to battery. Relay 409, upon energizing, at its armature 425 closes a circuit for the switching relay 408 in series with the motor magnet 443 and at armature 426 connects the test wiper 469 to the above circuit at a point midway between the switching relay and the said motor magnet. As the test contacts such as 461 are normally grounded in the banks of the finder switches such as F and this ground potential is removed only when a primary trunk line is seized as is the case when ground is removed from the test contact 461, a motor magnet 443 of the finder switch F will operate as a buzzer to advance the switch wipers 468—475, inclusive, until they are rotated into engagement with the set of bank contacts 460—467, inclusive, associated with the primary trunk line in use. During the operation of the motor magnet 443, the switching relay 408 is maintained short circuited by ground upon the successive test contacts and consequently does not energize. Immediately upon the trunk line terminating in bank contacts 460—467, inclusive, being seized, the short circuit is removed from relay 408 and the said relay energizes. Upon energizing, relay 408 at its armature 421 opens the circuit of the release magnets 447, 450 and 485 of the switches M, N and S of the switching discriminator SD, at front contact of this armature places ground upon the contact 481 in the bank of the distributor switch D, at armature 422 places ground upon the bank contact 460, at armature 423 places ground upon the test contact 461 in order to render the trunk line seized by finder F inaccessible to other finders which may be subsequently started, at armature 424 prepares an impulsing circuit for controlling the switching discriminator SD. The connection of ground to bank contact 481 of the distributor switch D causes the motor magnet 490 of that switch to be operated. This operation causes the distributor switch wipers 441 and 442 to be brought into association with an idle finder switch. The distributor switch D performs the function of extending the common starter wire 55 to an idle finder switch similar to the finder F. The operation of the distributor switch D opens the circuit of the starter relay 409 which deenergizes. However, after the energization of relay 408 and before the deenergization of relay 409 a circuit is completed extending from ground by way of armature 425 and its front contact, front contact and armature 422, back contact and armature 427, wiper 468, bank contact 460, conductor 56, and thru the winding of the relay 41 to battery. The relay 41 is energized over this circuit and, upon operating, at its armature 45 opens the circuit of the relay 40, at the front contact of this armature establishes a locking circuit for itself and places ground on the conductor 56 in order to maintain the switching relay 408 energized after the deenergization of relay 409, at its armature 46 removes ground from starting wire 55 and at front contact of this armature places ground on the conductor 57.

Returning now to the operation of the secondary line switch C', it will be remembered that the energization of the line relay 66 initiates its trunk hunting operation. When an idle trunk is found which, we will assume, is the trunk line terminating the bank contacts 84—87, inclusive, there will be no ground potential present upon the test contact 85 engaged by the test wiper 81 and the switching relay 65 being no longer short circuited, is energized in series with the motor magnet 67. The motor magnet, of course remains inoperative on account of the high resistance of relay 65. Relay 65, upon operating, prepares a controlling circuit for the switching discriminator SD at armature 73, at armature 72 places ground upon test contact 85 in order to busy the seized trunk line, at armature 71 prepares a holding circuit for the relay 41 of the relay group RG and the switching relay 13 of the line switch C, and at armatures 70 and 74 extends the calling subscriber's line by way of wipers 80 and 83, bank contacts 84 and 87, trunk conductors 96 and 99, thru the left hand windings of the repeating coil of the repeater R to the upper and lower windings of the line relay 130 of said repeater. The line relay 130 of the repeater R is energized over the calling subscriber's line and, upon operating, at its armature 132 completes a circuit for the slow acting relay 131, and at its armature 133 closes a bridge or repeating circuit across the trunk conductors 139 and 140 extending from the sub exchange 913 to the main exchange 91 where they terminate in an incoming first selector switch E. Relay 131, upon operating, at armature 136 prepares a point in a controlling circuit for the switching discriminator SD, at its armature 134 closes a point in a certain chain circuit which will be described later and at its armature 135 places ground upon the release trunk conductor 97, thereby establishing a holding circuit for the secondary line switch C'. This holding circuit may be traced from ground on trunk conductor 97 by way of bank contact 85, test wiper 81, to armature 72 and its front contact where the circuit divides one path extending thru the winding of the

switching relay 65 and the winding of the motor magnet 67 to battery, and the other path joining a previously traced holding circuit for the relay 41 of the relay group 5 RG and the relay 13 of the line switch C.

Upon the closure of the above mentioned repeating circuit in the repeater R, the line relay 150 of the incoming first selector E in the main exchange is energized over the 10 trunk conductors 139 and 140 in series. Relay 150, upon attracting its armature 160, closes the circuit of the slow acting relay 151. The latter relay, upon energizing, at armature 162 opens the circuit of the release 15 magnet 155, at the front contact of this armature prepares the impulsing circuits of the selector E and at armature 161 prepares a circuit for the relays 153 and 154.

It will be noted that the lower winding of 20 the line relay 150 of the selector E is connected thru the secondary transformer winding of tone machine T² to ground. Thus immediately upon the previously mentioned repeating circuit being closed, the calling 25 subscriber is given an audible signal in order to inform him that he may now operate his calling device. When the calling device is operated in accordance with the first digit 9, nine interruptions are produced 30 in the circuit of the line relay 130 of the repeater R and this relay deenergizes a corresponding number of times in response thereto. At each deenergization of the line 35 relay 130 the previously mentioned bridge across the trunk conductors 139 and 140 is opened. The nine interruptions produced by the calling device S at substation A are in this manner repeated to the line relay 150 of the selector E. At each deenergization 40 of the line relay 150 a circuit is closed for the vertical magnet 157 of the selector E in series with the slow acting relay 152. Magnet 157 operates to raise the switch wipers 171-173, inclusive, step by step until 45 they are placed opposite the ninth level of bank contacts. The slow acting relay 152 is energized in series with the vertical magnet and, upon the first vertical step of the switch, when the off normal springs are 50 shifted, a circuit is completed extending from ground by way of front contact and armature 161, armature 164 and its front contact, working contact of off normal spring 163 and the said spring, back contact 55 and armature 180 and thence thru the winding of the stepping relay 153 to battery. Relay 153, upon operating, at its armature 165 establishes a locking circuit for itself and at armature 166 prepares a circuit for 60 the rotary magnet 156. At termination of the vertical movement of the selector E the slow acting relay 152 deenergizes and at its armature 164 completes the circuit of the rotary magnet 156. Magnet 156 operates to 65 rotate the switch wipers into engagement

with the first set of bank contacts on the ninth level and at its armature 180 opens the locking circuit of the stepping relay 153. Relay 153 deenergizes thereby opening the circuit of the rotary magnet 156 which deenergizes also. Assuming that the trunk line associated with the first set of bank contacts on the ninth level is busy, there will be a ground potential upon the test contact 70 engaged by the test wiper 172 and the stepping relay 153 will again be energized. Relay 153 operates to establish a locking circuit for itself at armature 165 and to close the circuit of the rotary magnet 156 at armature 166. Magnet 156 rotates the switch 75 wipers into engagement with the next set of bank contacts on the ninth level and at armature 180 opens the locking circuit of the stepping relay 153 which deenergizes and opens the circuit of the rotary magnet which 80 deenergizes also. The alternate operation of the stepping relay 153 and the rotary magnet 156 continues until the switch wipers are brought into engagement with a set of bank contacts associated with an idle trunk 85 line, which, we will assume, are the bank contacts 174-176, inclusive. As soon as the wipers 171-173, inclusive, are brought into engagement with this set of bank contacts, the switching relay 154, which has been 90 short circuited during the operation of the selector E, is energized in series with the stepping relay 153. However, the latter relay is not operated at this time on account of the comparatively high resistance 95 of the switching relay 154. Relay 154, upon energizing, at its armature 168 places ground upon the test contact 175 in order to make 100 busy the seized trunk line, at armature 169 opens the circuit of the slow acting relay 105 151, at armatures 167 and 170 disconnects the windings of the line relay 150 from the trunk conductors 139 and 140, and at the front contacts of these armatures extends the said trunk conductors by way of wipers 110 171 and 173, bank contacts 174 and 176, trunk conductors 177 and 179 thru the windings of the line relay of the second selector E'.

The second selector E' is similar to the 115 first selector E in all respects except that the release trunk is extended back in a manner that has been completely shown in the fourth selector E', Fig. 12. Thus, when the connection is extended to the line relay of the selector E' this relay immediately energizes and closes the circuit of its associated slow acting release relay. The latter relay operates in the usual manner to prepare the 120 operating circuits of the second selector and to place ground upon the release trunk conductor 178 in order to establish a holding circuit to maintain the first selector E in an 125 operated position.

Adverting back to the operation of the 130

repeater R, when the first digit 9 is dialed, an additional result of the deenergizations of the line relay 130 is that at each retraction of the armature 132 an impulse of current is sent over the following circuit: From ground by way of the said armature and its back contact, armature 136 and its front contact, trunk conductor 98, bank contact 86, wiper 82, front contact and armature 73, conductor 58, bank contact 462, wiper 470, armature 424 and its front contact, thru the winding of the slow acting low resistance relay 407, wiper 440 of the sequence switch S in its first position and thence thru the winding of the vertical magnet 449 of the element N of the switching discriminator SD to battery. Magnet 449 operates to raise the switch wipers 437 and 438 step by step until they are brought opposite the level 15 of bank contacts corresponding to the first digit dialed which in this case is the digit 9. The slow acting relay 407 is energized in series with the vertical magnet 449 and, upon attracting its armature 420, closes the circuit of the slow acting relay 406. At the termination of the vertical movement of the element N the slow acting relay 407 de-energizes and opens the circuit of the slow acting relay 406. After the deenergization 20 of relay 407 and before the deenergization of relay 406 an impulse of current is sent to the operating magnet 486 of the sequence switch S. The sequence switch S is a simple rotary switch having an operating magnet 486 and release magnet 485, the rotary magnet 486 being adapted to actuate the wipers 439 and 440 upon each energization. Therefore, as an impulse of current is sent to the rotary magnet 486 of the said 25 switch, it operates to advance the wipers 439 and 440 into their second position.

When the calling device at substation A is operated in accordance with the next digit 1 of the desired number, an interruption is produced in the circuit of the line relay 130 of the repeater R. Relay 130, upon retracting its armature 133, repeats the digit to the line relay of the second selector switch E'. The line relay of the second selector E' controls the operation of the vertical magnet in stepping the switch wipers 200—202, inclusive, opposite the first level of bank contacts. The trunk selecting operation of the second selector is now initiated and takes place in a manner similar to that described in connection with the first selector E. When an idle trunk line is found, which, we will assume, is the trunk line terminating in bank contacts 206—208, inclusive, the switching relay of the selector E' is operated to disconnect the line relay of the said selector and to extend the trunk conductors 177 and 179 to the line relay of the third selector E².

The third selector E² is identical with the

second selector E'. Thus, immediately upon the extension of the trunk line to the line relay of the third selector, the said relay is energized to close the circuit of its associated slow acting release relay. The latter 70 relay operates to prepare the impulsing circuits of the third selector and to establish a holding circuit for the selectors E and E'.

Referring now to the operation of the repeater R, when the second digit 1 is dialed, 75 an impulse of current is sent to the element N of the switching discriminator SD over the same circuit as was traced in the first instance. However, inasmuch as the sequence switch S has been operated this impulse of current actuates the rotary magnet 448 and causes the wiper 438 of the element N to be rotated into engagement with the first contact of the ninth level. The slow acting relay 407 is energized in series with 80 the rotary magnet 448 and at the termination of the rotary impulse causes the sequence switch magnet 486 to operate, the latter operation stepping the wipers 439 and 440 into their third position. Upon the deenergization 85 of the slow acting relay 407, a circuit is completed extending from ground by way of back contact and armature 419, wiper 438, bank contact 91 of the element N, and thru the right hand winding of the relays 401, 403 and 404 in multiple to battery. The relays 401, 403 and 404 are of the shunt field type. That is, they do not attract their 90 armatures until both their windings are energized simultaneously. This is due to the fact that when only one winding is energized a magnetic short circuit exists so that the magnetic circuit does not include the relay armature. However, when both windings are energized together the magnetic circuit 95 includes the relay armature which is then attracted. Therefore it follows that even though the circuit of the right hand windings of the relays 401, 403 and 404 are closed these relays are not energized. The 100 movement of the wipers 439 and 440 of the sequence switch S into their third position transfers the impulsing circuit from the rotary magnet 448 of the element N to the vertical magnet 446 of the element M.

In response to the next operation of the calling device S at substation A for the digit 8, eight interruptions are produced in the circuit of the line relay 130 of the repeater R, and by the operation of this relay are repeated to the line relay of the third selector switch E² in the main exchange. The line relay of the third selector switch causes the vertical magnet to operate thereby stepping the switch wipers 210—212, inclusive, to the eighth level of bank contacts. The trunk selecting operation of the selector E² now takes place in the usual manner. Assuming that the trunk line shown in the drawings terminating in bank contacts 219—

- 221, inclusive, is the one selected, the connection is extended to the fourth selector E^3 . The line relay of that switch is energized and closes the circuit of its associated release 5 relay. This relay, upon operating, in addition to establishing the usual holding circuit for the precedingly operated selector switches, prepares the operating circuit of the fourth selector.
- 10 In the repeater R, the eight deenergizations of the line relay 130 cause eight impulses of current to be sent to the vertical magnet 446 of the element M of the switching discriminator SD. The magnet 446 15 operates to move the wipers 435 and 436 to the eighth level of bank contacts. As before, the slow acting relay 407 is energized in series with the vertical magnet 446 and at the termination of the magnet's operation 20 causes the sequence switch wipers 439 and 440 to step into their fourth position, thereby transferring the impulsing circuit from the vertical magnet 446 of the element M to the rotary magnet 445.
- 25 The calling subscriber at substation A may now operate his calling device for the fourth digit 2 of the number of the called substation A². By this operation two interruptions are produced in the circuit of the line 30 relay 130 of the repeater R and are repeated in the usual manner to the line relay of the fourth selector switch E^3 . The vertical magnet of the selector E^3 raises the wipers 225—227, inclusive, of the switch, opposite the second level of bank contacts under the control of the line relay. At the termination 35 of the vertical movement of the switch E^3 , its trunk hunting movement is initiated and takes place until an idle trunk line is 40 associated with its wipers, which, we will assume, is the trunk line terminating in the bank contacts 228—230, inclusive. As soon as the idle trunk line is found the switching 45 relay of the fourth selector E^3 is energized to extend the connection to the connector H.
- Immediately upon the extension of the connection, as above described, the line relay 301 of the said connector is energized and operates to close the circuit of the release 50 relay 302. Upon operating, the relay 302 at armature 314 opens the circuit of the release magnet 335, at the front contact of this armature prepares the operating circuits of the connector H, and at armature 313 places 55 ground upon the release trunk conductor 235, thereby establishing a holding circuit for the selectors E, E', E², and E^3 .
- At the repeater R the two deenergizations 60 of the line relay 130 cause two impulses of current to be sent to the rotary magnet 445 of the element M of the switching discriminator. The wiper 436 thereof is accordingly rotated into engagement with the second bank contact of the eighth level.
- 65 As this contact is dead there is no further operation of the relays in the relay group RG'. The slow acting relay 407, which is energized in series with the rotary magnet 445, at the termination of the rotary operation causes the wipers 439 and 440 of the sequence switch S to be advanced to their fifth position. As there has been no operation of the relays of the relay group RG', as soon as the sequence switch wiper 439 is advanced to its fifth position, a circuit is completed extending from ground by way of the sequence switch wiper 439 in its fifth position, back contact and armature 416, armature 417 and its back contact, and thru the winding of the relay 410 to battery. Relay 410, upon energizing, at its armature 427 opens the circuit of the switching relay 408 of the finder F. Upon deenergizing, the relay 408 completes the circuit of the release magnets 447, 450 and 485 of the elements M and N, and the sequence switch S, respectively. By the operation of these release magnets the various switches mentioned are restored to their normal position, the release magnet circuits being opened by off normal springs of the respective switches when they return to their normal position. By the deenergization of relay 408 all the circuits of the finder F and switching discriminator SD are restored to normal and this equipment reverts to common use so that it may be used for another connection. The release of this apparatus is brought about on account of the fact that the particular combination of digits dialed by the calling subscriber have determined that the call is going to the main exchange, or that it is necessary to complete the connection thru the main exchange and not by way of any one of the by-paths accessible to the line switches C⁴, C⁵, C⁶, C⁷ or C⁸.
- When the calling device at the calling substation A is operated in accordance with the next digit 6 of the desired number, six interruptions are produced in the circuit of the line relay 130 of the repeater R. By the operation of the armature 133 of the relay 130, these interruptions are repeated to the line relay 301 of the connector H which deenergizes a plurality of times in response thereto. At the first deenergization of the line relay 301, an impulse of current is sent to the vertical magnet 336 over a circuit extending from ground thru armature 312 and its back contact, armature 314 and its front contact, off normal springs 316 and 315, thru the winding of the slow acting relay 303, and thence thru the winding of the vertical magnet 336 to battery. The above is the circuit over which the first impulse to the vertical magnet is sent. However, upon the first operation of the switch shaft, the off normal springs are operated and the remaining vertical

magnet impulses traverse a new circuit which is similar to the one above traced, except that it includes the off normal springs 316 and 317, and armature 318 and 5 its front contact on the slow acting relay 303, which is now energized. Magnet 336 operates to raise the switch shaft carrying the switch wipers 340—342, inclusive, step by step until they are placed opposite the 10 sixth level of bank contacts. The slow acting relay 303 is energized in series with the vertical magnet and operates, as indicated before, to preserve the continuity of the vertical magnet when the off normal springs 15 are shifted.

In the repeater R the operation of the armature 132 of the line relay 130 is without further function, as the impulsive circuit including conductor 98 is opened by the 20 release of the switching discriminator SD.

When the calling device at substation A is operated in accordance with the next and final digit of the called number, which for convenience has been indicated by the letter 25 X, a series of interruptions is produced in the circuit of the line relay 130 of the repeater R, and these are repeated, in a manner similar to that already described, to the line relay 301 of the connector H. Relay 301, in response to this series of impulses, 30 deenergizes a plurality of times corresponding in number to the number of impulses in the digit dialed. At each deenergization of the line relay 301, an impulse of current is 35 sent over the following circuit: From ground by way of armature 312 and its back contact, armature 314 and its front contact, off normal springs 316 and 317, armature 318 and its back contact, back contact and armature 40 324, armature 331 and its back contact, and thru the winding of the rotary magnet 337 to battery. Magnet 337 operates to rotate the switch shaft carrying the switch wipers step by step until they are brought into engagement with the set of bank contacts associated with the line of the called substation, which it will be assumed are the bank contacts 343—345, inclusive. The slow acting 45 relay 306 is energized in multiple with the rotary magnet and, upon operating, at its armature 327 short circuits the armature 324 and its back contact on the test relay 305 in order to maintain the circuit of the rotary magnet closed while the switch wipers 50 are being rotated over bank contact sets associated with busy trunk lines, and at its armature 326 connects the test wiper 341 to the test relay 305. The operation of the connector H now depends upon whether the associated line is busy or idle.

Assuming first that the associated line is busy, ground will be connected to the test contact 344 and a circuit will be closed for the test relay 305. The latter relay, upon 55 energizing, prepares a locking circuit for

itself at armature 323 which is completed upon the deenergization of the slow acting relay 306, at armature 324 opens the rotary magnet circuit, and at armature 325 connects a lead from the busy signaling machine 70 to the lower heavy talking conductor. The latter operation gives the calling subscriber at substation A an audible signal which informs him that the desired called line is inaccessible for the present and he will have to 75 establish the desired connection at some later time. He will now replace his receiver upon the switch-hook. In response to this operation all the switches used in extending the connection to the line of the substation A² 80 are released in a manner which will be described hereinafter.

It will now be assumed that the line of the substation A² is idle when the switch wipers 340—342, inclusive, are brought into engagement with the bank contacts 343—345, inclusive. Under these conditions, there will be no ground potential upon the test contact 344 and no circuit will be completed for the test relay 305. Then, immediately upon the deenergization of the slow acting relay 306, a circuit is completed extending from ground on conductor 346 by way of armature 323 and its back contact, thru the upper winding of the switching relay 307, back contact and 90 armature 326, test wiper 341, test contact 344, thru the winding of the switching relay 350 of the line switch C², and thence thru the winding of the motor magnet 351 to battery. The switching relays 307 and 350 are energized over this circuit. However, due to a mechanical interlocking device under the control of the armature of the line relay 352, the switching relay 350 only partially attracts its armatures, enough to disconnect the 95 line of the called substation from its normal battery and ground connections in the line switch C². Upon energizing, relay 307 establishes a locking circuit for itself at armature 330, at armature 331 opens a point in the 100 circuit of the rotary magnet, at armature 329 connects direct ground to the test contact 344, and at armatures 328 and 332 completes the signaling circuit. Ringing current from the generator GEN is now intermittently projected out on the called line until an 105 answer is obtained.

When the called subscriber at substation A² removes his receiver a circuit is completed for energizing the ring cut off relay 304. Relay 304, upon operating, completes a locking circuit for itself at armature 320, at armatures 319 and 321 opens the ringing circuit, and at the front contacts of these armatures finally completes the talking connection. Conversation may now be carried on 120 between the calling subscriber at substation A and the called subscriber at substation A², talking current being supplied to the calling line from the windings of the line relay 125 130

130 of the repeater R and to the called subscriber from the windings of the back bridge relay 300 of the connector H. The latter relay is, of course, energized over the 5 called line loop and operates at its armatures 310 and 311 to reverse the direction of current flow in the conductors 234 and 236 for supervisory or metering purposes.

When the conversation is terminated both 10 subscribers will replace their receivers upon their switch-hooks. The release of the connection is brought about by the replacement of the receiver at the calling substation A. This operation opens the circuit 15 of the line relay 130 of the repeater R, which deenergizes, opening the circuit of its associated slow acting relay 131 and also the circuit of the line relay 301 of the connector H in the main exchange. The deenergization 20 of the relay 131 removes ground from the release trunk conductor 97, thereby opening the holding circuit of the relays 65, 41 and 13. The deenergization of these relays restores the secondary line switch C', the relay 25 group RG, and the primary line switch C to their normal positions. In the main office the deenergization of line relay 301 of the connector H, opens the circuit of the slow acting relay 302. The latter relay deenergizes to 30 complete the circuit of the release magnet 335 and to remove ground from the release trunk conductor 235. Magnet 335 operates to restore the connector H to its normal position in the usual manner. The removal of 35 ground from the release trunk conductor 235 opens the circuits of the switching relays of the first, second, third, and fourth selectors, E, E¹, E² and E³, respectively, thereby causing these switches to be restored to normal. 40 In the above manner all the apparatus used in extending the connection from the subscriber at substation A in the subexchange 913 to the subscriber at substation A² in the main exchange 91 is released.

45 Having described in detail the manner in which a connection is extended from a subscriber in the subexchange 913 to a subscriber in the main exchange 91, the manner in which connections are set up from the 50 subexchange 913 to the subexchange 9181 will now be briefly discussed. For this purpose, it will be assumed that the subscriber at substation A in the subexchange 913 desires to call the subscriber at substation A⁴ 55 in the subexchange 9181. In order to set up this connection it is necessary for the subscriber at substation A to remove his receiver and operate his calling device in accordance with the number 91817X.

60 When the receiver is removed at substation A, the individual line switch C operates to select and connect with an idle trunk line extending to a secondary line switch. It will be assumed that the trunk line shown in 65 the drawings is the one selected, the connec-

tion in this case being extended to the secondary line switch C'. The line switch C' operates to automatically select a trunk line extending to the main exchange 91. When the primary trunk line is seized the relay 40 70 is energized and initiates the operation of an idle finder switch, which, it will be assumed, is the finder F, to associate the switching discriminator SD with the trunk line in use. It will be assumed that the trunk 75 line extending to an incoming selector E in the main exchange by way of the repeater R is the one selected and connected with by the secondary line switch C'. The line and release relays 130 and 131 of the repeater R 80 energize and establish a holding circuit for the primary line switch C and the secondary line switch C'. The line relay 130 also closes the circuit of the line relay 150 of the incoming first selector E in the main office. 85

In response to the digits 918 of the desired number 91817X, the first selector E, a second selector such as E', and a third selector such as E², are operated in the same manner as was described in the first instance to 90 extend the connection to an idle fourth selector, such as E³. In the switching discriminator SD the wiper of the element N is raised to the ninth level and rotated in on the first contact and the wipers of the 95 element M are raised to the eighth level. All the operations outlined above take place in precisely the same manner as was described in the previous connection and will be readily understood. 100

When the calling device is operated for the fourth digit 1 of the desired number the line relay 130 of the repeater R operates to repeat this impulse to the line relay of the fourth selector E³. The wipers of 105 the selector E³ are accordingly raised opposite the first level of bank contacts and the automatic trunk selecting operation of the switch then takes place. It will be assumed that the trunk line terminating in 110 bank contacts 231-233, inclusive, is the one selected. In this manner a connection is extended to the repeater R². The line relay 240 of this repeater is immediately energized and closes the circuit of the slow 115 acting relay 241 at armature 244 and at its armature 242 completes a bridge across the trunk conductors 245 and 246 thru the left hand winding of the repeating coil. This bridge causes the energization of line relay 120 in an incoming connector switch in the subexchange 9181 which is similar to the connector switch H in every respect except that a portion of the release trunk is left out as it is not necessary for this connector 125 to complete a holding circuit for the switches in the main office, this being part of the function of the repeater R in order to dispense with a three conductor trunk line. The slow acting relay 241 at its armature 130

- 243 places ground upon release trunk conductor 249 thereby establishing the usual holding circuit for the precedingly operated selector switches.
- 5 The deenergization of the line relay 130 of the repeater R in response to the fourth digit 1 causes an impulse of current to be transmitted to the rotary magnet 445 of the switching discriminator SD and the 10 wiper 436 of the element M is rotated in on the first bank contact of the eighth level. At the deenergization of the slow acting relay 407, which is energized in series with rotary magnet 445, ground is placed upon the 15 wipers of the elements M and N, and in addition an impulse of current is sent to the operating magnet 486 of the sequence switch S. A circuit may now be traced extending from the grounded wiper 436 thru 20 bank contact 81 of the element M and thence thru the left hand winding of the shunt field relay 401. A circuit for the right hand winding of the relay 401 may now be traced from the grounded wiper 438 of the element 25 N by way of bank contacts 91 thru the right hand winding of the relay 401 to battery. As both windings of the relay 401 are now energized, this relay operates to attract its armature and a circuit is completed which 30 extends from ground thru the winding of the relay 405 by way of front contact and armature 412, wiper 474 of the finder F, bank contact 466, conductor 455, thru the winding of the slow acting line relay 508 35 of the line switch C' and thence to battery by way of the multiple chain contacts 525 and 526. The relays 405 and 508 are energized over this circuit before the sequence switch S is moved into its fifth position by 40 the operation of the magnet 486. Relay 405, upon energizing, opens a point in the energizing circuit of the relay 410 so that the latter relay does not operate at this time. In the line switch C', the relay 508, 45 upon operating, at its armature 511 completes a circuit for the switching relay 509 in series with the rotary magnet 510 and at armature 512 connects the test wiper 518 to the above circuit at a point between 50 the switching relay and the motor magnet. The trunk selecting operation of the line switch C' now takes place in the same manner as has been described before in connection with the trunk selecting operation of the line switch C. When 55 an idle trunk is found which, we will assume, is the trunk line terminating in bank contacts 530--532, inclusive, there being no ground potential upon the test contact 531, the switching relay 509 is immediately energized. Upon operating, relay 509 at its armature 513 connects ground to the test contact 531 in order to make busy the selected trunk line, at armature 514 60 places ground upon the conductor 60, and 65 at armatures 515 and 516 prepares a circuit for the line relay 645 of the repeater R'. The grounding of the conductor 60 causes the relay 42 of the relay group RG to be energized. The operation of this relay disconnects the primary trunk line conductors from connection with the secondary line switch C' at armatures 47, 48, and 49, and at the front contacts of these armatures transfers the trunk conductors over the conductors 59--61, inclusive, into connection with the repeater R' by way of the line switch C'. This operation causes the energization of the line relay 645 of the repeater R', which closes the circuit of the associated 70 slow acting relay 649 at armature 647, and at armature 646 places a bridge across the trunk conductors 650 and 651 extending to an incoming connector switch in the sub-exchange 9181. This connector is similar 75 to the one in which the trunk, comprising conductors 245 and 246 extending from the main exchange to the subexchange 9181, terminate. The energization of the slow acting relay 649 also places ground upon 80 the release trunk conductor 652 thereby establishing the usual holding circuit for the switching relay 509 of the secondary line switch C', the relay 42 of the relay group RG, and the switching relay 13 of the primary line switch C. 85
- It will be remembered that the energization of relay 42 of the relay group disconnects the primary trunk line from connection with the secondary line switch C' and the repeater R. The line relay 130 of the repeater R is accordingly deenergized and brings about the release of the line switch C', the relay 41 in the relay group RG, and the operated selectors E, E', E², and E³ in 90 the main exchange in a manner similar to that already described in connection with the usual release of the switches. When ground is removed from the release trunk 95 100 105 110 115 120 125 130
- In response to the two remaining digits 7X, the incoming connector in the sub-exchange 9181 in which the trunk line comprising conductors 650 and 651 terminate, is operated to complete the connection in the usual manner.
- When the conversation is terminated the replacement of the receiver at the calling substation A causes the deenergization of the line relay 645 of the repeater R'. The deenergization of the latter relay initiates the release of the incoming connector in the sub-exchange 9181, the secondary line switch C', and the primary line switch C. The relay 42 of the relay group RG also

restores to normal. In this manner all the apparatus involved in the connection is released.

The manner in which a connection is extended from the line of the substation A in the sub-exchange 913 to the line of the substation A⁶ in the sub-exchange 912, will now be described. For this purpose it will be assumed that in the previous connection the 5 subscriber at substation A instead of desiring the subscriber at substation A⁴ in sub-exchange 9181 desires the subscriber at substation A⁶ in the subexchange 912. The extension of the connection as far as the 10 third selector E², and the operation of the switching discriminator SD, for the digits 91, are the same as that described. However, as the subscriber at substation A desires to call the subscriber at substation A⁶ 15 the third digit will be 2 and in response to this digit the third selector E² is raised to the second level and automatically rotated to select an idle trunk line leading to the sub-exchange 912 by way of a repeater which it 20 will be assumed is the repeater R⁴. The line and release relays of this repeater operate to prepare a circuit for the line relay of an incoming fourth selector in the subexchange 912 and to establish a holding circuit for 25 the precedingly operated selector switches. 30

The operation of the line relay 130, of the repeater R, responsive to the third digit 2, causes two impulses of current to be sent to the vertical magnet 446 of the switching dis-

35 criminator SD. The operation of the vertical magnet 446 steps the wipers 435 and 436 opposite the second level of bank contacts and the vertical wiper 435 engages the vertical contact opposite the second level. 40 The slow acting relay 407 is energized in series with the vertical magnet and at the cessation of the impulse series deenergizes to place ground upon the wipers of the elements M and N and to cause a momentary 45 impulse of current to be sent to the operating magnet 486 of the sequence switch S. When ground is placed upon the wipers of the elements M and N, as the wiper 438 is now in engagement with the bank contact 91 50 of the element N and the wiper 435 in engagement with the vertical contact opposite the second level of the element M a circuit is completed for both windings of the shunt field relay 403. Upon energizing, 55 relay 403 completes a circuit extending over the following path: Ground thru the winding of the relay 405, front contact and armature 414, finder switch wiper 475, bank contact 467, conductor 456, thru 60 the winding of the line relay 540 and thence by way of multiple chain contacts such as 541 and 542 to battery. The line relay 540 of the line switch C⁸ is energized in series with relay 405. Relay 405 operates in the same manner as was described pre-

viously. The energization of the line relay 540 causes the secondary line switch C⁸ to operate in the usual manner to select an idle trunk line extending to the subexchange 912 by way of a repeater. It will be 70 assumed that the trunk line shown in the drawings terminating in bank contacts 545—547, inclusive is the one selected by the secondary line switch C⁸. The switching relay 550 is immediately energized and operates to prepare a circuit for the line relay 660 of the repeater R⁸. By the energization of the relay 550 ground is placed upon the conductor 60, thus completing a circuit for the relay 42 of the relay group RG. The relay 42 operates as before to disconnect the primary trunk from the repeater R and extend it to the repeater R⁸. The line relay 660 of the repeater R⁸ is immediately energized to close a bridge across the trunk conductors 666 and 667 and to complete the circuit of the slow acting relay 661. The latter relay prepares the usual holding circuit for the switching relay 550 of the line switch C⁸, the relay 42 of the relay group and the switching relay 13 of the primary line switch C. The disconnection of the primary trunk line from the repeater R, causes the secondary line switch C', the relay 41 in the relay group RG, the finder F, the switching discriminator SD, and the operated switches E, E', and E², to be released in the usual manner. 85

In response to the three remaining digits 78X, an incoming fourth selector and a connector in the sub-exchange 912 are operated to extend the connection to the line of the substation A⁶ in the usual manner. The incoming fourth selector switches and connector switches in the sub-exchange 912 are 90 similar in all respects to the incoming first selector E and the connector H, respectively, in the main office 91. 100

At the termination of the conversation, all the operated switches involved in the connection are released in a manner similar to that already described by the replacement of the receiver at substation A. 110

It will now be assumed that the subscriber at substation A instead of desiring to call a subscriber at substation A⁶ desires to establish a connection with the substation A⁵ in the main exchange 92. Therefore, when the connection is extended to the second selector E' in response to the digit 9, instead of operating his calling device S for the digit 1, he will operate it for the digit 2. The wipers of the second selector E' then automatically operate to select an idle trunk line extending to the main exchange 92. It will be assumed that the trunk line shown in the drawings terminating in bank contacts 203—205, inclusive, is the one selected for use. The line relay of the repeater R³ is immediately energized and closes a bridge across the 120 125 130

trunk conductors extending to an incoming third selector in the main exchange 92 and at the same time completes the circuit of its associated slow acting relay. The latter relay operates to place ground upon the release trunk conductor thereby establishing a holding circuit for the selectors E' and E. 5

In the repeater R the operation of the line relay 130 for the second digit 2 causes 10 two impulses of current to be transmitted to the rotary magnet 448 of the element N of the switching discriminator SD. The wiper 438 is therefore brought into engagement with the bank contact 92. The slow 15 acting relay 407 is energized in series with the rotary magnet and operates, as before, at the termination of the impulse series, to cause the operation of the sequence switch magnet 486 and to place ground on the 20 wiper 438. By the grounding of the wiper 438 a circuit is completed for the relay 402. Upon energizing, relay 402 at its armature 413 closes a circuit for relay 560 of the secondary line switch C⁶ in series with the relay 405. Relay 405 functions in the same 25 manner as before. The energization of the line relay 560 causes the secondary line switch C⁶ to operate to select an idle trunk line extending to an incoming third selector 30 in the main exchange 92 by way of a repeater. We will assume that the trunk line shown in the drawings terminating in the bank contacts 565-567, inclusive, is the one selected and connected with the secondary line switch C⁶. By the operation of the 35 switching relay 561 which takes place immediately after the selection of an idle trunk line, a circuit is prepared for the line relay of the repeater R⁶ and ground is also placed on conductor 60. Relay 42 is energized 40 immediately by the ground on conductor 60 and operates in the same manner as before, to transfer the primary trunk line from its connection with the repeater R into 45 connection with the repeater R⁶. The energization of the line relay of the repeater R⁶ takes place immediately and its operation serves to close a circuit for its associated slow acting relay and places a bridge 50 across the trunk conductors extending to an incoming third selector in the main exchange. The slow acting relay in the repeater R⁶ operates to establish a holding circuit for the switching relay 561 of the secondary line switch and the relays 42 and 13 in the same manner as before. The release of the secondary line switch C⁶, the relay 41 of the relay group RG, the finder F, the switching discriminator SD, and the operated first and second selectors E and E' in the main exchange, takes place as before. 55

When the calling device at the substation A is operated in accordance with the four remaining digits 556X, an incoming third selector in the main exchange 92, a fourth

selector and a connector, are operated to extend the connection to the desired line, that of the substation A⁵. The incoming third selector is similar to the incoming first selector E. The fourth selectors and connectors are of the same type as has been previously described. 70

When the conversation is terminated the replacement of the receiver at substation A initiates the release of the connection in a 75 manner similar to that already described in a preceding connection.

It will now be assumed that the calling subscriber instead of desiring a connection with a subscriber whose line is accessible thru any one of the adjoining exchanges, desires to establish a connection with a local subscriber at substation A⁵ in his own subexchange 913, the number of that subscriber being 91346X. Under these conditions 80 when the connection is extended to the third selector E² in the main exchange the calling device at the substation A will be operated for the third digit 3. By this operation the wipers of the third selector E² are raised 85 to the third level and are thereafter caused to automatically select an idle trunk line terminating in an incoming fourth selector in the subexchange 913, which it will be assumed is the trunk line shown in the drawings terminating in the bank contacts 213-215, inclusive, and extending by way of the repeater R⁵ to the incoming fourth selector E⁴ in the subexchange 913. The line relay 240' in the repeater R⁵ is immediately energized and operates to close the circuit of its associated slow acting relay 241' at armature 243' and to close the circuit of the line relay of the incoming selector E⁵. The slow acting relay 241' operates to 90 ground the release trunk conductor extending back to the other switches so as to maintain these switches in an operated position. The line relay of the incoming selector E⁴ is immediately energized and operates to close the circuit of its associated slow acting relay. The latter relay operates to prepare the operating circuits of this selector in the usual manner. 95

The deenergization of the line relay 130 of the repeater R in response to the third digit, cause the wipers of the element M of the switching discriminator SD to be brought opposite the third level of band contacts, thereby causing the wiper 435 to engage the third vertical bank contact. When ground is placed on the wipers of the elements M and N at the deenergization of the slow acting relay 407, a circuit for both windings of the relay 404 is completed. Upon energizing, relay 404 completes a circuit for the line relay 501 of the secondary line switch C⁴ in series with relay 405. The line relay 501, upon energizing, initiates the trunk hunting operation of the secondary 100 105 110 115 120 125 130

line switch C⁴. When an idle trunk is found, which we will assume is the trunk line terminating in bank contacts 580-582, inclusive, the switching relay 502 is immediately energized. Upon operating, the latter relay prepares a circuit for the line relay 701 of the local fourth selector E⁵. A further result of the energization of the relay 502 is that a circuit is completed for the relay 42 of the relay group RG. By the operation of the relay 42 the primary trunk is transferred from connection with the repeater R into connection with the fourth selector E⁵, Fig. 12. The line relay 701 of the fourth selector E⁵ is immediately energized and closes the circuit of its associated slow acting release relay. The latter relay operates to prepare the impulsing circuits of the selector E⁵ and to place ground upon the release trunk conductor 591 thereby establishing a holding circuit for the secondary line switch C⁴, the relay 42 of the relay group RG and the switching relay 13 of the primary line switch C. As soon as the primary trunk line is transferred to the fourth selector E⁵ the trunk line extending to the main exchange, and the operated switches therein, together with the secondary line switch C', the relay 41 of the relay group RG, the finder F and the switching discriminator SD, are released in the same manner as has already been described.

In response to the fourth digit 4 the wipers 720-723, inclusive, of the selector E⁵, are raised opposite the fourth level of bank contacts. At the termination of the vertical movement of the selector the trunk selecting operation of the switch begins. When an idle trunk line is found, which it will be assumed is the trunk line terminating in bank contacts 724-726, inclusive, the switching relay 705 is energized. Upon operating, relay 705 extends the connection to the connector switch H'. The line relay 750 immediately energizes to complete the circuit of the slow acting relay 760. The latter relay completes the usual holding circuit for the preceedingly operated switches and prepares the impulsing circuits of the connector H'. Only a portion of the circuits of the connector H' have been shown; however, it will be understood that this connector is similar to the connector H, Fig. 8.

In response to the two remaining digits 7X the connector switch H' is operated in the usual manner to extend the connection to the line of the substation A³, terminating in bank contacts 782-784, inclusive, of the connector H. When the conversation is terminated the release of the primary line switch C, secondary line switch C⁴, fourth selector E⁵ and the connector H', takes place in a well-known manner in response to the replacement of the receiver at substation A.

Having described the manner in which

connections are established between the subscriber at substation A and various other subscribers located within the subexchange 913 and adjoining exchanges, the manner in which the subscriber at substation A is enabled to call a subscriber on his own line will now be briefly explained. For this purpose it will be assumed that the subscriber at substation A desires to call the subscriber at substation A'. In order to do this the subscriber at substation A will remove his receiver, operate his calling device for the digit 0 and then replace his receiver on the switch hook.

When the receiver is removed the operation of selecting an idle trunk line extending to an incoming first selector in the main exchange, and the association of a switching discriminator with the primary trunk line seized, takes place in the same manner as has been previously described. That is, the primary line switch C operates to select a trunk line extending to the secondary line switch, which we will assume is the trunk line shown in the drawings extending to the secondary line switch C'. The secondary line switch C' thereupon operates to select and connect with an idle trunk line leading to a first selector in the main exchange, and it will be assumed that the trunk line terminating in bank contacts 84-87, inclusive, is the one connected with. The line relay 130 of the repeater R is immediately energized to close the circuit of the line relay 150 of the incoming first selector E in the main exchange, which immediately energizes to close the circuit of the associated slow acting release relay. In addition, the line relay 130 of the repeater R establishes a circuit for its associated slow acting relay 131 which operates to establish a holding circuit for the line switches C and C'. By the seizure of the primary trunk line, an idle finder switch, which we shall assume is the finder F, is started operating, in order to associate a switching discriminator SD with the seized trunk line.

In response to the digit 0, ten interruptions are produced in the circuit of the line relay 130 of the repeater R and by the successive deenergizations of this relay, are repeated to the line relay 150 of the incoming first selector E in the main exchange. The line relay 150 in its operations, controls the vertical magnet 157 in stepping the switch wipers of the selector E, opposite the tenth level of bank contacts. When the vertical movement ceases the trunk hunting operation of the selector is initiated. As the digit 0 is used for retractive calls in the subexchange, the tenth level of the selector E will be dead and in this case the trunk hunting operation is without function.

Referring again to the operations of the line relay 130 of the repeater R in response

to the digit 0, ten impulses are sent to the vertical magnet 449 of the element N of the switching discriminator SD in series with the slow acting relay 407. The vertical magnet 449 operates to raise the shaft carrying the wipers 437 and 438 step by step until they are brought opposite the tenth level of bank contacts. By this operation, the vertical wiper 437 is brought into engagement with the tenth vertical bank contact. Upon the deenergization of the slow acting relay 407, which takes place immediately upon the cessation of the vertical magnet impulses, an impulse of current is sent to the operating magnet 486 of the sequence switch S and the vertical wiper 437 is grounded. The magnet 486 operates to advance the sequence switch wipers 439 and 440 into their second position. By the grounding of wiper 437 a circuit is completed for the relay 400 of the relay group RG. Upon energizing, relay 400 at its armature 411 closes a circuit for the line relay 590 of the secondary line switch C⁵, in series with the relay 405 thru the chain contacts 591 and 592. The operation of the relay 405 is without function at the present time. The energization of the relay 590 of the secondary line switch C⁵ causes the trunk hunting operation of this line switch to be initiated. The trunk selecting operation of the line switch C⁵ takes place in the usual manner. When the switch wipers 596—598, inclusive, are brought into engagement with the bank contacts associated with an idle trunk line, which it will be assumed are the bank contacts 585—587, inclusive, the switching relay 595 energizes to prepare a point in the circuit of the line relay 602 of the ring back equipment K. In addition the energization of relay 595 causes a circuit to be completed for the relay 42 of the relay group RG. The relay 42 operates, as before, to disconnect the primary trunk line from the repeater R and to connect it to the ring back equipment K. The line relay 602 of the ring back equipment K is immediately energized and operates at its armature 611 to close the circuit of the slow acting relay 603. The latter relay energizes and at its armature 606 operates to place ground upon release trunk 610 thereby establishing a holding circuit for the switching relay 595 of the line switch C⁵, the relay 42 of the relay group RG and the switching relay 13 of the primary line switch C. When the primary trunk line is disconnected from the repeater R, the secondary line switch C', the relay 41 of the relay group RG, the finder F, the switching discriminator SD, the trunk line extending to the main exchange, and the first selector E therein, are released. When the receiver is replaced at the substation A the line relay deenergizes, and at its armature 612 completes a circuit of the relay 601. Upon energizing, the latter relay at armature 629 completes a locking circuit for the slow acting relay 603, at armature 630 prepares an interrupted circuit for the slow acting relay 613, and at armatures 628 and 631 disconnects the line relay 602, and at the front contacts of these armatures completes the ringing circuit. When the interrupter I sends an impulse of current to the slow acting relay 613, this relay energizes to connect a lead from the generator GEN' to the conductor 641, which is associated with the line conductor 12 of the substation A. The signaling device at substation A is connected from the line conductor 12 to ground and is consequently operated by the current from the generator GEN'. Another result of the energization of the relay 613 is that at armature 618 a circuit is completed for the slow acting relay 614. The latter relay, upon operating, at its armature 620 prepares a circuit for the slow acting relay 615. As there is but a momentary impulse of current sent to the slow acting relay 613 by the interrupter I this relay deenergizes after a short interval whereby ringing current is disconnected from the line conductor 12 and an impulse of current is sent to the slow acting relay 615. Upon operating, relay 615 at armature 621 connects a lead from the generator GEN' to the trunk conductor 640 which is associated with the line conductor 11 of the calling line. Ringing current sent out over line conductor 11 operates the signaling device at substation A', which is connected from the line conductor 11 to ground. A further result of the energization of the relay 615 is that at armature 622 the ring cut off relay 616 is associated with the conductor 641 and consequently the line conductor 12. A short time after the deenergization of slow acting relay 614, which takes place shortly after the retraction of the armature 618 of the relay 613, relay 615 deenergizes thereby connecting the ring cut off relay to the conductor 640 and placing ground upon the conductor 641. When the next impulse of current is sent to the slow acting relay 613 from the interrupter I the same cycle of operations again take place and in this manner the ringers of the substations A and A' are actuated alternately until the subscriber at the called substation A' removes his receiver. When the receiver is removed at the substation A' a circuit is completed for the ring cut off relay 616 which is immediately energized over the line conductors 11 and 12 in series. Upon operating, relay 616 establishes a locking circuit for itself at armature 624 and at armature 623 opens the circuit of relay 601. Relay 601 immediately retracts its armatures to interrupt the signaling circuit and to reconnect the windings

of the line relay 602 with the conductors 640 and 641. The line relay 602 is energized over the calling line and at its armature 611 closes a circuit for the slow acting relay 603 before this relay has had time to deenergize, due to the fact that its circuit has been opened by the deenergization of the relay 601. As the signaling device at substation A is now no longer operated the calling subscriber thereat will know that the party at the desired substation has answered and will consequently remove his receiver. The calling subscriber at substation A and the called subscriber at substation A' may now converse, talking current being supplied to both substations from the windings of the line relay 602 of the ring back switch K.

When the conversation is terminated the release of the ring back equipment K, the secondary line switch C⁵ and the primary line switch C are brought about by the replacement of the receiver at both substations A and A'. The replacement of the receivers causes the deenergization of the line relay 601 which opens the circuit of the slow acting relay 603. The deenergization of the relay 603 removes ground from the release trunk conductor 610 whereby the above mentioned switches are released.

30 All the typical connections of the system having been described, certain special provisions which have been made in order to safeguard the operation of the system will now be explained.

35 It sometimes happens that when the receiver is removed at a calling substation in the subexchange 913, all the trunks extending to the main office are busy. Under these conditions it is necessary to provide equipment so that the calling subscriber is not precluded from extending a connection by way of any one of the by-paths accessible thru the secondary line switches associated with the primary trunk lines. In order to handle this situation a number of bank contacts in the secondary line switches, such as C', with which there are no trunk lines extending to the main exchange associated, are connected to dummy repeaters, such as the one shown at R'. The trunk lines leading to the repeaters such as R' are normally busy. When all the trunk lines to the main exchange become busy the repeaters such as R' are made accessible to the secondary line of switches in the following manner. As soon as all the trunk lines to the main exchange become busy a circuit is completed for the relay 190 thru the chain contacts such as 125, 126, and 134 on the regular repeaters such as R. The relay 190, upon energizing, removes the ground potential from the test contacts associated with the trunk lines extending to the dummy repeaters such as R', thus rendering these repeaters accessible to the secondary line

switches. In order to describe the operation when all the trunks to main are busy, it will be assumed that the subscriber at substation A desires to extend a connection when all the trunk lines to the main exchange are in use.

In the above case, when the receiver is removed at the substation A the primary line switch C is operated in the usual manner to select and connect with an idle primary trunk line, which we will assume is the trunk line terminating in the bank contacts 29—31, inclusive. As soon as the calling subscriber's line is extended to the secondary line switch C' by the energization of the switching relay 13 of the primary line switch C the trunk selecting operation of the secondary line switch C' is initiated. As all the trunk lines extending to the main exchange are busy the line switch C will select a trunk line extending to a dummy repeater such as R, and it will be assumed that the trunk line terminating in bank contacts 88—91, inclusive, is the one selected. The switching relay 65 of the secondary line switch C is immediately energized and operates to extend the calling subscriber's line to the line relay 106 of the repeater R'. Upon energizing, line relay 106 closes a circuit for the slow acting relay 108. Relay 108, upon operating, places ground upon the release trunk conductor 93 thereby establishing a holding circuit for the primary line switch C and the secondary line switch C'. It will be noted that instead of going to direct ground the lower winding of the line relay 106 is connected thru the secondary winding of the transformer of the tone machine T to ground. The calling subscriber is accordingly given the so-called trunk tone in order to inform him that he may operate his calling device.

When the primary trunk line is seized the relay 40 energizes and an idle finder switch, which we will assume is the finder F, is automatically operated to associate the switching discriminator SD with the primary trunk line.

When the calling device at substation A is operated in accordance with the first digit a series of interruptions is produced in the circuit of the line relay 106 of the repeater R', which deenergizes a plurality of times in response thereto. At each deenergization, an impulse of current is sent to the vertical magnet 449 of the element N of the switching discriminator SD over the following circuit: Ground by way of back contact and armature 113, front contact and armature 119, conductor 94, bank contact 90, wiper 82, front contact and armature 73, conductor 58, bank contact 462 of the finder F, wiper 470, armature 424 and its front contact, sequence switch wiper 440 in its first position, and thru the winding of the

vertical magnet 449 to battery. The vertical magnet raises the switch shaft carrying the wipers 437 and 438 opposite the level of bank contacts corresponding to the digit 5 dialed. The slow acting relay 407 is energized in series with the vertical magnet and controls the operation of the sequence switch magnet 486 in the usual manner.

From the above it will be seen that the 10 elements M and N of the switching discriminator SD are operated in the same manner as if a trunk line has been selected to a main exchange. Thus if the calling subscriber desires to obtain connection with a 15 subscriber located in an exchange which is accessible from any one of the line switches C⁴, C⁶, C⁷ or C⁸, the connection may be established in the same manner as has been previously described. However, if the calling 20 subscriber desires to obtain a connection with a subscriber in the main exchange, none of the secondary line switches associated with the primary trunk line will be operated and after the dialing of the fourth digit 25 the sequence switch wipers 439 and 440 will be stepped into their fifth position. By the operation of the sequence switch wiper 440 ground is placed upon the impulsing lead extending back to the repeater R' and consequently the relay 105 therein is energized. Upon operating, relay 105 at its 30 armature 110 establishes a locking circuit for itself and at armature 111 places the busy tone from the busy machine on the lower conductor. In this manner the calling subscriber at substation A is informed that he cannot obtain connection with the 35 desired line at the present time and he will replace his receiver thereby bringing about the release of the connection in the usual manner.

It may also happen that when a calling subscriber in initiating a call desires to obtain a connection with a subscriber in one of 40 the exchanges which is accessible thru one of the secondary line switches, C⁴, C⁶, C⁷ or C⁸, that all the trunk lines extending to selectors in this exchange are busy. In order to describe the operation in this case, it will be assumed that when the calling subscriber 45 at substation A desires to extend a call to a subscriber at substation A⁴ in the subexchange 9181, that all the trunk lines accessible to the secondary line switch C⁷ are 50 busy. When all the trunk lines accessible to the secondary line switch C⁷ are busy all the chain contacts such as 526 will be opened and, upon the operation of the shunt field relay 401, there will be no circuit completed 55 for the relay 405 or for the line relay 508 of the line switch C⁷. The line switch C⁷ does not function at this time. When the sequence switch wipers 439 and 440 are 60 stepped into their fifth position by the operation of the magnet 486 at the termination 65

of the fourth series of impulses, a circuit is completed extending from ground by way of bank contact and wiper 439, back contact and armature 416, armature 417 and its back contact, and thru the winding of the relay 70 410 to battery. Upon operating, relay 410 at its armature 427 opens the holding circuit of the switching relay 408 of the finder F. By the deenergization of the switching 75 relay 408 the elements M and N, the sequence switch S, and the relay equipment in the relay group RG' as well as the finder F are restored to normal.

In the main exchange the fourth selector 80 E³, at the termination of the fourth digit, automatically selects a trunk line extending to an incoming connector in the subexchange 9181. The connection may now be completed in response to the operation of the calling device at the calling substation over 85 the trunk line from the main exchange in a well known manner.

When the conversation is terminated the release of the connection is brought about 90 in the usual manner by the replacement of the receiver at the calling substation.

From the above it will be seen that a calling subscriber in a subexchange is enabled to extend a connection to a subscriber in another exchange than his own over a 95 shorter route than is provided by the regular trunking system. If any one of these routes become busy or inaccessible to him he is enabled to extend a connection to the desired subscriber thru the ordinary trunking system. Again, if all the trunks that he ordinarily uses to the main exchange are busy he is enabled to complete the connection over one of the bypasses if he desires a subscriber 100 whose line is located in any other one of the 105 accessible exchanges.

The features of the invention having been described and ascertained, what is considered to be new and desired to have protected by Letters Patent will be pointed out in the 110 appended claims.

What is claimed is:

1. In a telephone system, a trunk line having a plurality of branches, a recording device, means for connecting said device to said trunk line over a circuit path exclusive of said branches, an automatic switch associated with each branch of said trunk line, means for seizing said trunk line and for operating one of said automatic switches over one of said branches to extend a connection in the direction of a called line, means for operating said recording device in synchronism with said switch, means controlled by said recording device for releasing the operated switch, and circuit connections controlled by said recording device for then enabling another automatic switch to be operated over another of said branches. 120
2. In a telephone system, a trunk line 125

130

- having a plurality of branches, a recording device, means for seizing said trunk line and for connecting said recording device therewith over a circuit path exclusive of said branches, an automatic switch associated with one of said branches, means for operating said switch over the last named branch to extend a connection in the direction of a called line, and means controlled by said recording device for releasing said switch if said switch is operated in accordance with a predetermined digit of the called number.
3. In a telephone system, a trunk line having a plurality of branches, a recording device, means for seizing said trunk line and for associating said recording device therewith, an automatic switch, means for operating said switch over one of said branches to extend a connection in the direction of a called line, and means controlled by said recording device and operative if said switch is operated in accordance with a predetermined digit for associating another of said branches with said trunk line so that the connection may be completed over said second branch.
4. In a telephone system, a trunk line having a plurality of branches, a recording device, means for seizing said trunk line and for associating said recording device therewith, automatic switches, means for sending controlling impulses over one branch of said trunk line to operate a series of said switches to extend a connection in the direction of a called line, and means controlled by said recording device for releasing said branch and series of switches if a certain combination of controlling impulses in accordance with certain predetermined digits are sent over said branch.
5. In a telephone system, a trunk line having a plurality of branches, a recording device, means for seizing said trunk line and for associating said recording device therewith, automatic switches, means for sending controlling impulses over one branch of said trunk line to operate a series of said switches to extend a connection in the direction of a called line, means controlled by said recording device for releasing said branch and series of switches if a certain combination of controlling impulses, in accordance with certain predetermined digits, are sent over said branch, and for causing subsequent controlling impulses to operate another series of switches over another of said branches.
6. In a telephone system, a trunk line having a plurality of branches, a recording device, means for seizing said trunk line, means operative responsive to the seizure of said trunk line for associating said recording device therewith, a separate group of automatic switches accessible over each of said branches, means for sending impulses over said trunk line, means controlled by said impulses to operate automatic switch over only one of said branches, and means operative if certain predetermined digits are called for causing said operated switches to release.
7. In a telephone system, a trunk line having a plurality of branches, a recording device, means for seizing said trunk line, means operative responsive to the seizure of said trunk line for associating said recording device therewith, a separate group of automatic switches accessible over each of said branches, means for sending impulses over said trunk line, means controlled by said impulses to operate automatic switches over one of said branches, means operative if certain predetermined digits are called for causing said operated switches to release, means then operative to cause any subsequent impulses to operate automatic switches accessible over another of said branches.
8. In a telephone system, a first exchange, a plurality of other exchanges, a trunk line in said first exchange having a plurality of branches, one branch for each of said other exchanges, groups of automatic switches accessible to said branches, respectively, a recording device associated with said trunk line, means for seizing said trunk line and for thereupon extending a connection automatically over one of its branches to a second exchange, means for operating a series of switches over said connection, and means controlled by said recording device, operated after certain pre-determined digits corresponding to a portion of a number of a subscriber's line in one of said other exchanges are sent out, for causing the release of said connection and the establishment of a connection over another of said branches to the exchange in which the desired line terminates.
9. In a telephone system, a first exchange, a plurality of other exchanges, a trunk line in said first exchange having a plurality of branches, one branch for each of said other exchanges, groups of automatic switches accessible to said branches, respectively, a recording device associated with said trunk line and for thereupon extending a connection automatically over one of its branches to a second exchange, means for operating a series of switches over said connection, means controlled by said recording device, operated after certain pre-determined digits corresponding to a portion of a number of a subscriber's lines in one of said other exchanges are sent out, for causing the release of said connection and the establishment of a connection over another of said branches to the exchange in which the desired line terminates.

nates, and means for completing the connection to the called line in the last named exchange over the last mentioned connection.

10. In a telephone system, a main exchange, a plurality of branch exchanges varying in size, a switching repeater for use in branch exchanges, means controlled by said repeater for switching any call to one of said branch exchanges from said main exchange when sufficient digits have been called to determine its destination, and means for causing said switching repeater to switch on either the first, second, third or fourth digit in a called number whereby the switching repeater may be used to switch calls to branch exchanges of different sizes.

11. In a telephone system, a main exchange, a plurality of branch exchanges, means including a switching device for connecting a calling subscriber in one of said branch exchanges with a called subscriber in any one of said exchanges, rotary line switches associated with said device, trunk lines to the main and other branch exchanges each accessible through one of said rotary line switches, means for operating the line switch having access to trunk lines extending to said main exchange whenever said device is taken for use, means for giving the calling subscriber a busy signal in case all said main exchange trunk lines are busy, and means for rendering said last mentioned means inoperative until the calling subscriber has called such digits as determine definitely that the call in order to be successful must be completed by way of one of said main exchange trunk lines.

12. In a telephone system, main and branch exchanges, means including a switching device for connecting a calling subscriber in one of said branch exchanges with a called subscriber in any one of said exchanges, rotary line switches associated with said device, trunk lines to the main and other branch exchanges each accessible through one of said rotary line switches, means for operating the line switch having access to trunk lines extending to said main exchange whenever said device is taken for use, means for giving the calling subscriber a busy signal in case all said main exchange trunk lines are busy, and means for rendering said last mentioned means inoperative if the calling subscriber calls such digits as determine that the call may be completed by way of one of said other line switches to a subscriber in any one of said branch exchanges.

13. In a telephone system, a trunk line having a plurality of individual branches each terminating in an automatic switch, means for extending a calling line to said trunk line, a registering device and means for connecting it to said trunk line when the same is taken for use, means controlled

by the calling subscriber for operating said registering device in accordance with a digit in a called number, and circuit connections between said registering device and said switches for automatically operating a particular switch after the digit is called.

14. In a telephone system, a trunk line having a plurality of individual branches each terminating in an automatic switch, means for extending a calling line to said trunk line, a registering device and means for connecting it to said trunk line when the same is taken for use, means controlled by the calling subscriber for operating said device in accordance with a plurality of digits in a called number, and circuit connections between said device and said switches for automatically operating a particular switch after said digits are called.

15. In a telephone system, a trunk line having a plurality of individual branches each terminating in an automatic switch, means for extending a calling line to said trunk line, a registering device and means for connecting it to said trunk line when the same is taken for use, means for operating a first one of said switches when the trunk line is taken for use, means operated through a contact on the operated switch for setting said device in accordance with a digit in the called number, and means controlled by said device for operating one of said other switches in case said device is set for a particular digit.

16. In a telephone system, a trunk line having a plurality of individual branches each terminating in an automatic switch, means for extending a calling line to said trunk line, a registering device and means for connecting it to said trunk line when the same is taken for use, a group of trunk repeaters accessible to a first one of said switches, means for operating said first switch to seize an idle repeater when the trunk line is taken for use, subscriber controlled means in said repeater for setting said device in accordance with a digit in a called number, and circuit connections between said device and the other of said switches for operating one of said other switches, the switch operated depending on the setting of said device.

17. In a telephone system, a trunk line having a plurality of individual branches each terminating in an automatic switch, means for extending a calling line to said trunk line, a registering device common to said trunk line and other similar trunk lines, automatic switching mechanism for connecting said device to said first trunk line when the same is taken for use, means controlled by the calling subscriber for setting said device in accordance with a digit in the called number to select one of said

switches for operation, and means for automatically operating the selected switch independent of the subscriber.

18. In a telephone system, a main exchange, two sub-exchanges, trunk lines connecting each exchange with each of the others, automatic switches in the main exchange controlled by a calling subscriber in the first sub-exchange to select a trunk line from the main exchange to the second sub-exchange, a registering device in the first sub-exchange set simultaneously with the operation of said switches, and means controlled by said device for selecting a trunk line extending from the first sub-exchange to said second sub-exchange.

19. In a telephone system, a main exchange, two sub-exchanges, trunk lines connecting each exchange with each of the others, automatic switches in the main exchange controlled by a calling subscriber in the first sub-exchange to select a trunk line from the main exchange to the second sub-exchange, a registering device in the first sub-exchange set simultaneously with the operation of said switches, means controlled by said device for selecting a trunk line extending from the first sub-exchange to said second sub-exchange, and means for releasing said switches while the calling line is maintained connected with the last selected trunk line.

20. In a telephone system, a main exchange, three sub-exchanges, trunk lines connecting each exchange with each of the others, automatic switches in the main exchange controlled by a calling subscriber in the first sub-exchange to select a trunk line from the main exchange to either the second or third sub-exchange depending on the number called, a registering device in the first sub-exchange set simultaneously with the operation of said switches, and means controlled by said device for selecting a trunk from the first sub-exchange to the second sub-exchange or a trunk from the first sub-exchange to the third sub-exchange, depending on the setting of said device.

21. In a telephone system, a main exchange, three sub-exchanges, trunk lines connecting each exchange with each of the others, automatic switches in the main exchange controlled by a calling subscriber in the first sub-exchange to select a trunk line from the main exchange to either the second or third sub-exchange depending on the number called, a registering device in the first sub-exchange set simultaneously with the operation of said switches, means controlled by said device for selecting a trunk from the first sub-exchange to the second sub-exchange or a trunk from the first sub-exchange to the third sub-exchange, depending on the setting of said device, and means operative in either case for releasing the said

switches while the calling line is maintained in connection with the last selected trunk line.

22. In a telephone system, two registers, a switching circuit, means for operating said registers responsive to two succeeding digits, respectively, of a telephone number, two relay windings, a circuit for each winding, means controlled by the first register, when operated by a particular digit, to close the circuit of the first relay winding, means controlled by the second register, when operated by a particular digit, to close the circuit of the second relay winding, and means responsive to the closure of both relay winding circuits for closing said switching circuit.

23. In a telephone system, trunks, a switching discriminator common to said trunks, a normally connected branch and a normally disconnected branch for each trunk, means responsive to a seizure of one of said trunks for associating said discriminator with such trunk, means responsive to the calling of certain digits of a number for partially setting up a connection over said normally connected branch and for disconnecting such branch and connecting up the other branch, other means responsive to the calling of said digits for disassociating said switching discriminator from the trunk, and means in said discriminator responsive to the dialling of a larger number of digits for disassociating said discriminator from the trunk.

24. In a telephone system, a trunk line, a switching discriminator, means responsive to a seizure of said trunk line for connecting said discriminator with said trunk line, a magnet for operating said discriminator mechanically, a pair of contacts individual to said trunk line, and means for operating said magnet through said contacts.

25. In a telephone system, a switching discriminator, a trunk line having a normally connected branch and a normally disconnected branch, a plurality of automatic switches connected in multiple across said normally disconnected branch, means for transmitting digits representing part of a telephone number over said trunk and over said normally connected branch, means for simultaneously operating said discriminator to register such digits, and means controlled by said discriminator and dependent upon the part of the number called for operating one of said plurality of switches and for shifting said trunk from said normally connected to said normally disconnected branch to extend the connection over said operated switch.

26. In a switching discriminator, a plurality of relays and a switch mechanism for operating them, said mechanism having a primary movement and a secondary move-

- ment, means for operating said switch in its primary movement to select a group of contacts and for operating it in its secondary movement to connect with a particular contact in the selected primary group, and two wipers for said switch, one for engaging bank contacts during the primary movement and the other for engaging bank contacts during the secondary movement, whereby the desired one of said relays may be operated, either at the end of the primary or at the end of the secondary movement of the said switch. 5
27. In a telephone system, a plurality of trunk lines, a switching discriminator, switching mechanism, means responsive to a seizure of any one of said trunk lines for operating said mechanism to connect said discriminator with such trunk line, a magnet for operating said discriminator mechanically, a pair of contacts individual to the seized trunk line, and means for operating said magnet through said contacts. 10
28. In a telephone system, a plurality of trunk lines, a switching discriminator, a finder switch individual to said discriminator, means responsive to a seizure of any one of said trunk lines for operating said finder switch to connect said discriminator with such trunk line, a magnet for operating said discriminator mechanically, a pair of contacts individual to the seized trunk line, and means for operating said magnet through said contacts. 15
29. In a telephone system, a trunk line having two main branches, sub-branches into which one of said main branches is divided, means for extending a call to said trunk line at the undivided end thereof, and means for routing the call away from said trunk line over any one of said branches. 20
30. In a telephone system, a trunk line having two main branches, sub-branches into which one of said main branches is divided, means for extending a call to said trunk line at the undivided end thereof, registering mechanism and means for associating the same with said trunk line responsive to the seizure thereof, and means controlled by said registering mechanism for routing the call from said trunk line over any one of said branches. 25
31. In a telephone system, a trunk line having two main branches, sub-branches into which one of said main branches is divided, means for extending a call to said trunk line at the undivided end thereof, registering mechanism, an automatic switch responsive to the seizure of said trunk line for connecting said mechanism therewith, and means controlled by said registering mechanism for routing the call from said trunk line over any one of said branches. 30
32. In a telephone system, a trunk line having two main branches, one of said
- branches terminating in an automatic switch, sub-branches into which the other main branch is divided, automatic switches terminating said sub-branches, means for extending a call to said trunk line at the undivided end thereof, means responsive to the seizure of the trunk for operating said first switch, and subscriber controlled means for operating any one of the other switches at will and for releasing said first switch while holding the trunk seized. 35
33. In a telephone system, a trunk line having two main branches, one of said branches terminating in an automatic switch, sub-branches into which the other main branch is divided, automatic switches terminating said sub-branches, means for extending a call to said trunk line at the undivided end thereof, means responsive to the seizure of the trunk for operating said first switch, subscriber controlled means for operating any one of the other switches at will and for releasing said first switch while holding the trunk seized, said last means comprising registering mechanism with means for associating it with the said trunk 40
- when the same is taken for use. 45
34. In a telephone system, a trunk line terminating in an automatic switch, a branch of said trunk line having a plurality of sub-branches each sub-branch also terminating in an automatic switch, means for extending a call to said trunk line, means normally effective to route the call from the trunk line via said first switch, and subscriber controlled means whereby the call 50 can be rerouted via any one of the other switches without releasing the trunk. 55
35. In a telephone system, a trunk line, an automatic repeater, an automatic switch, means for seizing said trunk line and operating said automatic switch to extend a connection from said trunk line to said repeater, said connection including an impulse conductor, a line relay in said repeater operated over said connection to repeat impulses, a recording device, and contacts on said repeating relay for repeating impulses over said impulse conductor to operate said recording device. 60
36. In a multi-office telephone system, a plurality of trunk lines out-going from a particular office, a repeater associated with and individual to each of said trunk lines, a plurality of local trunk lines for use in setting up local connections and in setting up outgoing connections, means for seizing any one of said local trunk lines, a secondary switch responsive thereto for setting up a connection through a repeater to the corresponding outgoing trunk line, means in said repeater operating simultaneously with the repeating of impulses to the outgoing trunk line for operating said local switching mechanism to complete the connection locally in case a local subscriber is desired, other repeaters similarly accessible to said 65

secondary switch but not associated with outgoing trunk lines, and means responsive to the condition of all the first named repeaters being busy for extending any calling local trunk line to one of said other repeaters.

37. In a telephone system, a trunk line having a plurality of branches, a switching discriminator, means for seizing said trunk line, means responsive thereto for connecting said switching discriminator to said trunk line, a sequence switch in said discriminator responsive to a fixed number of digits for severing the connection between said trunk line and said switching discriminator, means in said switching discriminator for routing the call over the correct branch operative responsive to a variable number of digits less in number than said fixed number of digits, and means responsive to such directive action of said switching discriminator for also severing said connection.

38. In a telephone system, a trunk with three branches, three branch connecting relays, registering means controlled over said trunk for registering digits in a telephone number, and means responsive to the registration of a particular series of digits for energizing a particular one of said relays, the relay energized depending on the series of digits registered.

39. In a telephone system, a trunk having a plurality of normally disconnected branches, a relay for each branch for connecting the same with said trunk line, registering means controlled over said trunk for registering digits in telephone numbers, and means responsive to the registration of different series of digits for separately energizing said relays.

40. In a telephone system, a trunk line having a plurality of normally disconnected branches, each associated with a different exchange, a registering device associated with said trunk line for registering the digits in the exchange designations of called lines, the said branches being maintained disconnected while such digits are being registered, and means responsive to the registration of the last digit in any exchange designation for connecting up the particular branch which is associated with the exchange corresponding to the registered digits.

41. In a telephone system, a trunk line having a plurality of normally disconnected branches, each associated with a different exchange, a registering device associated with said trunk line for registering the digits in the exchange designations of called lines, the said branches being maintained disconnected while such digits are being registered, individual relays for connecting said branches to the trunk line, and means responsive to the complete registration of any exchange designation for operating the proper relay

to connect up the branch associated with the exchange which corresponds to the registered exchange designation.

42. In a telephone system, a trunk line in two normally disconnected sections, means for registering series of impulses received over the first section, a relay for connecting said sections, means for energizing said relay responsive to the registration of the first series only if the first series has a particular value, and means for energizing said relay responsive to the registration of the second series if the first series has a different value.

43. In a telephone system, a trunk line in two normally disconnected sections, means for registering series of impulses received over the first section, a relay for connecting said sections, and means for energizing said relay responsive to the registration of either the first or the second series of impulses depending on the value of the said first series.

44. In a telephone system, an automatic switch, a group of trunk lines accessible to said switch, a plurality of auxiliary switches individual to said switch and having access to a plurality of other groups of trunk lines, respectively, means for operating the first named automatic switch to seize a trunk line in the associated group, and means operative thereafter for releasing the seized trunk line and for operating one of said plurality of auxiliary switches to extend the connection over a trunk line in the associated group.

45. In a telephone system, a line having two outgoing branches, means including two directly controlled switching devices for effecting the initial extension of said branches, respectively, means for operating only one of said switching devices in accordance with a digit in a telephone number whereby the associated branch is extended, and means responsive to such digit for rendering the other switching device responsive to the following digit in the number to extend the other branch.

46. In a telephone system, a line having two outgoing branches, means including two directly controlled switching devices for effecting the initial extension of said branches, respectively, means for operating only one of said switching devices in accordance with a digit in a telephone number whereby the associated branch is extended, and means responsive to such digit for releasing the operated switch and for rendering the second switching device responsive to the following digit.

47. In a telephone system, a line having two outgoing branches, a directly controlled automatic switching device associated with the first branch and responsive to a digit in a telephone number to extend such branch, means responsive to such digit for disconnecting the first branch from the line and for connecting the second branch to the

line, and an automatic switch individual to the second branch and rendered initially operative upon said second branch being connected up.

5 48. In a telephone system, a line having two outgoing branches, means including a directly controlled automatic switching device associated with the first branch for extending that branch only responsive to a 10 given digit in a telephone number, and means responsive to such digit for releasing the operated device and for connecting the second branch to the trunk line.

49. In a telephone system, a line comprising 15 two telephonically connected sections, means for extending the second section of said line in accordance with the final digit in a telephone number, a line, and means responsive to such digit in case it indicates 20 said line for disconnecting the first section of said line from the second section and for extending such first section to said last line.

50. In a telephone system, a line divided 25 into two branches, directly controlled switching mechanisms associated with said branches, respectively, means controlled over said line and over the first branch for operating the associated mechanism in accordance with a digit in a telephone number, 30 the switching mechanism associated with the other branch being non-responsive to such digit, and means effective in case the said digit has a particular value for rendering the first switching mechanism non-responsive 35 to further control and for rendering the second mechanism responsive to control over the line and over the second branch.

51. In a telephone system, a line, two directly controlled switching devices for 40 extending said line, means for operating only one of said devices responsive to a given digit in a telephone number, means responsive such digit for rendering the second switching device responsive to the following digit in said number over a circuit 45 path independent of the first switch.

52. In a telephone system, a line, said line having two branches, means responsive to a portion of a telephone number for extending 50 only one of said branches toward a called line, and means also responsive to such portion for releasing such extension and for enabling the second branch to be extended toward a called line in accordance 55 with the remaining portion of the number.

53. In a telephone system, a line having two branches, directly controlled automatic switching mechanism for extending the first branch, similar mechanism for extending 60 the second branch, other similar lines, and a registering mechanism operated over any one of said lines to determine which of the two branches of such line shall be used to complete a connection.

54. In a telephone system, a line having

two branches, directly controlled automatic switching mechanisms for extending said branches, other similar lines, and a registering mechanism common to all said lines and controlled over any one of them 70 for controlling the connection of the branches of such line therewith.

55. In a telephone system, a trunk line having two branches, directly controlled switching mechanism for extending the first 75 branch, directly controlled switching mechanism for extending the second branch, and a registering device separate from said branch extending mechanisms for controlling the connection between the trunk line 80 and its branches.

56. In a telephone system, a trunk line having two branches, automatic non-numerical switches individual to said branches, respectively, means responsive to the seizure 85 of said trunk line for operating only one of said automatic switches, and means responsive to the transmission of impulses representing a portion of a telephone number for releasing the operated switch and for 90 operating the other switch.

57. In a telephone system, a trunk line, two automatic switches individual thereto, two groups of trunk lines accessible to said switches, respectively, an impulse repeater 95 inserted in each of the trunk lines in one of said groups, means responsive to call over the first said trunk line for operating the one of said switches associated with the repeater-group of trunk lines to select a 100 trunk line in the associated group, registering apparatus, means in the repeater individual to the seized trunk line for operating said registering apparatus in accordance with the called number, and means controlled by said registering apparatus for releasing the operated one of said switches 105 and for causing the other to select an idle trunk in the associated group.

58. In a telephone system, a trunk line 110 having two branches, automatic non-numerical switches individual to said branches, respectively, means responsive to the seizure of said trunk line for operating only one of said automatic switches, a third branch, 115 and means controlled over said third branch responsive to the transmission of impulses representing a portion of a telephone number for releasing the operated switch and for operating the other switch.

59. In a telephone system, a trunk, two automatic switches individual thereto, two groups of trunks accessible to said switches, respectively, means responsive to a call over said trunk for operating one of said 125 switches to select a trunk in the associated group, registering means associated with the last named trunk, said registering means being operated over said last named trunk in accordance with the called number, and 130

means controlled by said registering means for releasing the last named one of said switches and for causing the other of said switches to select an idle trunk in the associated group.

60. In a telephone system, a trunk, an automatic switch associated with said trunk, a group of trunks accessible to said switch, means responsive to a call over said trunk 10 to cause the said switch to select an idle trunk in the associated group, a second automatic switch associated with the first named trunk, a switching relay, and means controlled from the trunk seized by the first 15 named switch for energizing said switching relay to release said first named switch and to operate the second of said switches to seize an idle trunk in the associated group.
61. In a telephone system, a trunk, an automatic switch associated with said trunk, a group of trunks accessible to said switch, means responsive to a call over said trunk to cause the said switch to select an idle trunk in the associated group, a second automatic switch associated with the first named trunk, a switching relay, and means controlled from the trunk seized by the first named switch for energizing said switching 25 relay to release said first named switch and to operate the second of said switches to 30 seize an idle trunk in the associated group, said means being effective or not in accordance with the number called.

62. In a main-exchange and branch-ex-

change telephone system, a trunk line in the branch exchange, means for connecting this trunk line with a calling line, a branch-to-main trunk line extending from a repeater in the branch exchange to a selector in the main exchange, means responsive to the connection of the said branch-exchange trunk line to the calling line for connecting the said branch-exchange trunk line with said branch-to-main trunk line, means in said repeater for repeating the series of impulses 40 representing the called number over the trunk line to the main exchange to operate switching means including the selector on the distant end of the branch-to-main trunk line to complete the connection, a registering 45 device in the branch exchange operated by contacts in said repeater simultaneous with the repeating of the impulses to the main exchange, a local-connection trunk line, and means controlled by said register in case the 50 number desired is a branch exchange number for disconnecting said branch-exchange trunk line from said branch-to-main trunk line and for connecting it instead to said local trunk line whereby the branch-to-main 55 trunk line is freed for use by other subscribers and the connection is completed over the local trunk line to the desired local subscriber.

In witness whereof, I hereunto subscribe 60 my name this 10th day of April, A. D. 1922.

ARTHUR J. RAY.
